AUTOMATIC BELTMaking MACHINE

Joseph Raggi, New York, N. Y.

Application June 22, 1949, Serial No. 100,730

34 Claims. (Cl. 59—3)

1

This invention relates to new and useful improvements in an automatic belt making machine.

More particularly, the present invention relates to a self-contained machine which is fully automatic in its operation to form a belt from a plurality of interengaged links connected with a suitable tongue in a manner so that the belt need only be completed by the addition of a buckle upon being discharged from the machine.

Another object of the present invention proposes the construction of a belt making machine including a punch operated in timed relation with the other mechanisms of the machine to continuously cut the links from a continuous strip of material in a manner so that the links will be available to be interlinked by the machine to form the belt.

A further object of the present invention proposes the provision of mechanism for continuously drawing the strip of material from a roll thereof and feeding it to the punch of the machine in a manner to have the links cut therefrom.

Still another object of the present invention proposes providing the machine with link feeding mechanism for conveying the links from the punch and engaging them with the proper slots of the belt being formed in the machine and which operates in timed relation with the punch to carry each link as completed from the punch to the belt being formed.

A still further object of the present invention proposes the provision of a novel mechanism for holding the belt being formed on a tongue member with its proper slot aligned with the link feeding mechanism in a manner to insure that each link conveyed by the link feeding mechanism will be engaged with the proper slot of the belt being formed or a tongue member.

Still further the present invention proposes constructing the belt holding mechanism to include a pair of feed rollers between which the belt being formed is disposed with mechanism for periodically rotating the feed rollers in a manner to feed the belt being formed downward following each engagement of a link in a manner to align another slot of the belt being formed with the link feeding mechanism.

As the slots of the belt being formed, with which the links are engaged, are slots of the links, those slots are shorter than the width of the links, therefore, the present invention proposes novel mechanism for curling the sides of the link being conveyed by the link feeding mechanism in a manner to permit it to be engaged

2

with the slot of the belt being formed by the link feeding mechanism.

It is a further object of the present invention to provide the machine with mechanism for uncurling the link after it has been engaged with the belt being formed and for holding the inserted link in position in a manner to permit the link feeding mechanism to be withdrawn without withdrawing the link from the slot of the belt being formed.

The invention further proposes the providing of a novel counting mechanism associated with the machine and which is adjustable to be preset to control the number of links which will be interengaged to form any one belt in a manner to permit the machine to form belts of different lengths.

Still another object of the present invention proposes the provision of a novel release mechanism associated with the counting mechanism in a manner to be operated thereby to free the formed belt to drop from the bottom of the machine after the desired number of links have been engaged therewith.

25 A further object of the present invention proposes the provision of a novel magazine containing a plurality of preformed tongues mounted on the machine to be operated in timed relation with the counting and belt release mechanisms to free one of the contained tongues to drop into the machine and be drawn into proper position by the feed rolls.

A still further object of the present invention proposes forming the magazine with suitable mechanism to insure that only one tongue will be dropped from the magazine upon each operation thereof.

The present invention proposes so constructing the belt making machine that operation of the punch and the link feeding mechanism will be temporarily suspended during the time that the completed belt is being dropped from the machine and the new tongue is being fed into the machine in a manner to insure that the new tongue will be in its proper position before any additional links are fed toward the belt holding mechanism.

It is a further object of the present invention to provide the machine with mechanism controlled by the dropping of the tongue to release the punch and link feeding mechanism for continued operation when the proper slot of the tongue is in alignment with the link feeding mechanism.

Still another object of the present invention

proposes connecting the counting mechanism with the mechanism controlled by the dropping of the tongue in a manner to insure that the counting mechanism will be reset to "zero" each time the punch and link feeding mechanism is released for continued operation.

Another object of the present invention proposes providing the belt making machine with a single rotative cam for controlling the operation of the various mechanisms in a manner to insure their operation in the proper timed relationship.

A still further object of the present invention is the construction of a belt making machine which is fully automatic in its operation so that it needs no attention from the operator beyond the periodic replacement of the supply of material from which the links are punched and the periodic replenishment of the supply of pre-formed tongues in the magazine.

It is a further object of the present invention to construct a belt making machine which is simple and durable and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 27 is a diagrammatic plan view illustrating the movement of the belt link toward engagement with the previously engaged links.

Fig. 28 is a view similar to Fig. 27, but illustrating a different position of the parts.

Fig. 29 is a diagrammatic vertical view looking in the direction of the line 29—29 of Fig. 28.

Figs. 30, 31 and 32 are further views similar to Figs. 27 and 28, but illustrating still further positions of the parts.

Fig. 33 is a vertical sectional view taken on the line 33—33 of Fig. 32.

Fig. 34 is a plan view of the operative parts of the link feeding mechanism when moving in a direction to pick up a link to be inserted.

Fig. 35 is a vertical sectional view taken on the line 35—35 of Fig. 34.

Fig. 36 is a plan view similar to Fig. 34 illustrating the position of the parts of the link feeding mechanism when the link has been picked up.

Fig. 37 is a vertical sectional view taken on the line 37—37 of Fig. 36.

Fig. 38 is a plan view similar to Fig. 36 illustrating the position of the parts of the link feeding mechanism when they start their movement in a direction to engage the picked up link with the belt being formed.

Fig. 39 is a vertical sectional view taken on the line 39—39 of Fig. 38.

Fig. 40 is a view similar to Fig. 38, but illustrating a different position of the parts.

Fig. 41 is a vertical sectional view taken on the line 41—41 of Fig. 40.

Fig. 42 is a view similar to Fig. 40, but illustrating a still further position of the parts.

Fig. 43 is a vertical sectional view taken on the line 43—43 of Fig. 42.

Fig. 44 is a view similar to Fig. 42, but illustrating the picked up link partially engaged with the belt being formed.

Fig. 45 is a vertical sectional view taken on the line 45—45 of Fig. 44.

Fig. 46 is a view similar to Fig. 44, but illustrating the link completely engaged with the belt being formed.

Fig. 47 is a vertical sectional view taken on the line 47—47 of Fig. 46.

Fig. 48 is a view similar to Fig. 46, but illustrating the parts of the link feeding mechanism when they move away from the belt being formed after the picked up link has been engaged therewith.

Fig. 49 is a vertical sectional view taken on the line 49—49 of Fig. 48.

The automatic belt making machine, according to the present invention, includes a frame 60 comprised of a casing having a top wall 61, a front wall 62, a rear wall 63 and end walls 64. The bottom of the casing is closed by means of a platform 65 which has its top face abutted against a flange 66 formed within the casing. Four legs 67 are provided for supporting the casing in a suitable elevated position and for holding the platform 65 in its position closing the open bottom of the casing. The legs 67 are formed adjacent their top ends with shoulders

68, upon which depending flanges 69 from the casing rest, with the top portions of the legs 67 extended along the inside face of the flanges 69 and with the bottom face of the platform 65 resting upon the top ends of the legs 67. Nut and bolt assemblies 70 are extended through the overlapped portions of the flanges 69 and the top portion of the legs 67 securely attaching the legs to the casing.

The front wall 62, the rear wall 63 and the right hand end wall 64, as the machine is viewed in Fig. 1, are formed with openings 71 closed by means of thin metallic plates 72 held in position by removable screws 73. On some of the views of the drawings, the plates 72 have been omitted for the sake of clarity of illustration. As the plates 72 are formed of thinner material than the material from which the casing is formed, the use of the plates materially lightens the weight of the machine and also provides a convenient means for providing access to the mechanisms contained within the casing.

All power for the operation of the machine is derived from a continuous belt illustrated partially at 74 in Figs. 1 and 6 to 8. The belt 74 engages over a pulley 75 forming part of the machine and removed from the machine, that belt engages over a driving pulley (not shown) mounted on the driven shaft of an electric motor (not shown) or the like for causing the pulley 75 to be continuously rotated when the motor is energized. The pulley 75 is fixedly mounted on a shaft 76 rotatively supported in a suitable bearing member 77 integrally formed with a U-shaped bracket 78 supported to depend from the platform 65. The bearing member 77 is hollow and encloses a spaced pair of thrust bearings 79, see Fig. 6, through which the shaft 76 is extended to be rotatively supported thereby.

The top portion of the shaft 76 is sleeved by a tubular shaft 80. The tubular shaft 80 is vertically slidably but non-rotatively connected with the shaft 76 by means of a key 81, see Fig. 6. The top end of the tubular shaft 80 is integrally formed with a clutch disc 82 which has secured to its top face a friction pad 83, by means of several rivets 84. The top face of the friction pad 83, which may be of rubber or cork, is arranged to make contact with a second clutch disc 85 which is fixedly secured to a shaft 86, by means of a key 87. The shaft 86 is rotatively supported by spaced thrust bearings 88 nested in a bearing block 89 positioned within an opening 90 formed in the platform 65, see Fig. 6. A cam disc 90, to be hereinafter described in greater detail, is mounted on the top end of the shaft 86.

Means is provide for retaining the tubular shaft 80 in a raised position on the shaft 76 for retaining the clutch discs 82 and 85 in an engaged position in which they will function to continuously rotate the shaft 86 and the cam disc 90 when the shaft 76 is rotated. The retaining means comprises an expansion spring 91 concentrically engaged about the shaft 76 and which operates between the bottom end of the tubular shaft 80 and a collar 92. The collar 92 is rotative on the shaft 76 and rests on a shoulder 93 formed on the shaft 76, see Fig. 6. Thus, the spring 91 retains the tubular shaft 80 in a raised position on the shaft 76 to retain the friction pad 83 in facial engagement with the clutch disc 85 so that the clutch discs 82 and 85 function as a normally closed clutch for driving the shaft 86 from the shaft 76.

The U-shaped bracket 78 is supported upon the platform 65 by several tie rods 94 which depend from the bottom face of the platform 65. The tie rods 94 have reduced bottom portions 95 which pass through complementary openings formed in the intermediate arm of the U-shaped bracket 78. The reduced bottom portions 95 are threaded and have engaged thereon nuts 96. The top ends of the side arms of the U-shaped bracket 78 are formed with reduced tongue portions 97 which extend into complementary grooves 98 formed in the bottom face of the platform 65. The engagement of the tongue portions 97 with the grooves 98 assists the tie rods 94 in supporting the U-shaped bracket 78 against movement in a horizontal plane relative to the bottom face of the platform 65.

A punch 99 is supported on the left-hand end of the casing, as viewed in Fig. 1, for stamping the links to be used for forming the belt from a continuous strip of material 100. The strip of material is as wide as the links forming the belt and is wound into a roll 101, see Fig. 1, which is rotatively mounted on a pin 102 which extends from an arm 103 mounted on one of the legs 67.

The punch 99 comprises a plate 104, see Figs. 1 and 6, positioned over an opening 105 formed in the left-hand end wall 64 of the casing, and which plate is secured in position by means of nut and bolt assemblies 106. Integrally formed with the plate 104, there is a pair of spaced laterally extending arms 107. Rotatively extended between the outer ends of the arms 107 there is a pair of superimposed shafts 108 and 109. Fixedly mounted on the lower shaft 108 there is a driven roller 110 and fixedly mounted on the upper shaft 109 there is an idler roller 111. A gear 112 is integrally formed on the back side of the driven roller 110 and that gear meshes with a complementary gear 113, see especially Fig. 5, formed on the back side of the idler roller 111 to cause the idler roller 111 to be rotated when the driven roller 110 is rotated.

The contacting surfaces of the rollers 110 and 111 are coated with a layer of rubber 114 to grip and feed the strip of material drawn from the roll 101 when the rollers 110 and 111 are rotated. Means, to be hereinafter described, is provided for periodically turning the driven roller 110 causing the rollers 110 and 111 to rotate to feed the strip of material 100.

Specific details of the construction of the punch 99 are illustrated in Figs. 4, 5 and 14 to 16 and it is comprised of a bed 115 integrally formed with the arms 107 between the rollers 110 and 111 and the casing. Nested in the bed 115 there is a fixed die member 116. Extended vertically from the top face of the bed 115 there are four vertical posts 117, see Figs. 15 and 16. The bottom ends of the posts 117 are formed with reduced portions 118 passed through complementary holes formed in the bed 115 and upon which nuts 119 are threaded for securing the posts 117 to the bed 115. The top ends of the posts 117 are also formed with reduced portions 120 which are passed through complementary holes formed in a top plate 121. Threadedly engaged upon the top ends of the reduced portions 120 there are nuts 122 for attaching the top plate to the posts 117. Accordingly, the posts 117 function to support the plate 121 parallel to and at a fixed position above the bed 115.

Slidably mounted on the posts 117 between the

adjacent faces of the bed 115 and the plate 121, there is a carrier 123. The carrier 123 is formed of metal and has secured thereto a movable die member 124. The central portion of the movable die member 124 is secured to the carrier 123 by several screws 125, see Fig. 15, and has its ends secured to the carrier 123 by nut and bolt assemblies 126, see Fig. 14. To increase the thickness of the carrier 123 where the posts 117 slidably pass therethrough, the carrier 123 is provided with bushings 127 which project below the bottom face of the carrier 123 and which slidably encircle the posts 117. Blocks 128 are extended along the sides of the carrier 123 over the projected bottom ends of the bushings 127 and are secured in position by means of screws 129, see Fig. 16. Increasing the thickness of the carrier 123, by means of the bushings 127 and the blocks 128, causes the carrier 123 to move vertically on the posts 117 without twisting with a resulting binding action on the posts 117 which would interfere with free vertical movement of the carrier.

Resilient means is provided for urging the carrier 123 toward the fixed die member 116 with sufficient pressure to insure that the movable die member 124 will cooperate with the fixed die member to cut the links from the strip of material 100. The resilient means is characterized by an expansion spring 130 which has its bottom end seated on the top face of the carrier 123. The top end of the spring 130 is extended through a hole 131 formed in the top plate 121 and has its top end seated about a projection 132 formed on the bottom face of the intermediate arm of an inverted substantially U-shaped bracket 133. The side arms of the bracket 133 extend along the sides of the spring 130 and have their free ends extended laterally outward along the top face of the top plate 121 and secured thereto by means of screws 134, see Fig. 15.

Means operated by the cam disc 90 is provided for holding the carrier 123 in a raised position against the action of the expansion spring 130 and for freeing the carrier to move the movable die member 124 toward the fixed die member 116 under the influence of the spring 130. This means comprises a rod 135, see Figs. 4, 6, 7 and 14, rotatively extended through complementary openings 136 formed in the arms 137. Fixedly mounted on the rear end of the rod 135, there is a lever 137 and fixedly mounted on the front end of the rod there is an arm 138. The lever 137 and the arm 138 are extended parallel to one another, but the arm 138 is somewhat longer than the lever 137. The free end of the arm 138 is projected into the casing through an aperture 139 formed in the plate 104, see Fig. 6, and through the opening 105 of the respective end wall 64. The inner end of the arm 138 rotatively supports a roller 140 to roll on the top face of the cam disc 90 as the cam disc rotates.

Links 141 have their bottom ends pivotally supported on the lever 137 and the arm 138, closely adjacent the rod 135, by means of pivot pins 142. The links 141 are formed with reduced top end portions 143 which are slidably and turnably extended into complementary slots 144 formed in ears 145 which are integrally formed with and project laterally from the sides of the top plate 121. The reduced top portions 143 of the links 141 are of a width considerably less than the width of the links and continue from

rounded portions 146, see Fig. 6, against which the bottom faces of the ears 145 rest.

The top face of the cam disc 90 is formed at its outer periphery with a cam surface 147, see Fig. 26, consisting of a raised portion 148 and a lower portion 149. The raised portion 148 is considerably longer than the lower portion 149 and the adjacent ends of the portions 148 and 149 are connected by inclined surfaces 150 and 151 to permit the roller 140 to pass from the raised portion 148 to the lower portion 149 and vice versa. When the roller 140 is on the raised portion 148 of the top cam surface 147 the arm 138 and the lever 137 will be in a raised position in which the carrier 123 will be raised against the action of the expansion spring 130 holding the movable die member 124 raised off the fixed die member 116, as illustrated in Figs. 14 and 15. However, when the roller 140 rolls into the lower portion 149 of the top cam surface 147, the lever 137 and the arm 138 will be free to be lowered under the influence of the spring 130 which acts to lower the top plate 121 and the movable die member 124 toward the fixed die member 116.

As shown most clearly in Fig. 27, the links 152 cut from the strip of material 100 and which are to be interlinked to form the belt, each have a rounded head portion 153, a reduced neck portion 154 and a larger body portion 155. The rounded head portion 153 is formed with a single slot 156 and the body portion 155 is formed with a pair of slots 157 and 158. The slots 156, 157 and 158 are slightly longer than the width of the neck portion 154 and in forming the belt each link 152 is folded across its neck portion 154 so as to align the slot 156 with the slot 157, as will become clear as this specification proceeds.

The die members 116 and 124 are arranged in a novel way to first shape the head and neck portions of the link and to cut the slots 156, 157 and 158 after which the free end of the body portion 155 is shaped, as shown in Fig. 3. To carry this out, the fixed die member 116, see Fig. 4, has a portion 159 shaped to the form of the head portion 153 and the neck portion 154 of the link 152 and a plurality of openings 160 corresponding to the slots 156, 157 and 158. Forward of the portion 159, the fixed die member 116 has a portion 161 shaped to the form of the free end of the body portion 155 of the link 152. The movable die member 124 is formed with three depending portions 162 arranged to enter the openings 160 and form the slots 156, 157 and 158 of the links 152. The movable die member 124 also carries a depending portion 163 arranged to engage about the portions 159 and 161 when the movable die member 124 is lowered toward the fixed die member 116. The bed 115 which supports the fixed die member 116 is formed with appropriately located openings 164, see Figs. 14 and 15, through which the punched out portions of the strip of material 100 drop to discharge from the machine.

Arranged in connection with the movable die member 124, there is a resiliently mounted pressure plate 165 to fixedly clamp the strip of material 100 in position on the top face of the fixed die member 116 during the link punching operation. The plate 165 has a plurality of shanks 166 extended vertically therefrom and slidably projected through complementary holes formed in the die member 124 and the carrier 123. The top ends of the shanks 166 are threaded and engaged by complementary nuts 167 which rest on the top face of the carrier 123 and prevent withdrawal of the shanks 166. Expansion springs 168

are concentrically engaged upon the shanks 166 and operate between the adjacent faces of the pressure plate 165 and the die member 124 urging the pressure plate 165 into a lowered position in which its bottom face will be flush with the bottom ends of the depending portions 162 and 163 of the movable die member 124, as shown in Figs. 14 and 15.

The strip of material 100 is as wide as the links 152 and is periodically fed between the adjacent faces of the die members 116 and 124 by the rollers 110 and 111. When the strip of material 100 has been fed the proper amount, the roller 140 will roll into the lower portion 149 of the top cam surface 147 of the cam disc 90 freeing the movable die member 124 to be lowered toward the fixed die member 116 by the spring 130. First, the pressure plate 165 will engage the top face of the strip of material 100 and clamp it against the top face of the fixed die member 116 to securely hold the strip of material in position.

Further downward movement of the movable die member 124 will cause its depending portions 162 and 163 to enter the fixed die member 116 to shape the free end of the body portion 155 of the foremost link 152 and simultaneously shape the head portion 153, neck portion 154 and the slots 156, 157 and 158 of the next rearmost link 152, as shown in Fig. 3. This action frees the foremost link to be drawn into the machine by the link feeding mechanism to be hereinafter described. The act of not completely severing the next rearmost link 152 from the strip of material insures that the partially formed link will be advanced to the proper position to be picked up by the link feeding mechanism on the next movement of the strip of material 100. When the roller 140 again rides on the raised portion 148 of the top cam surface 147, the movable die member 124 will be raised off the fixed die member 116, against the action of the spring 130, disengaging its depending portions 161 and 162 from the fixed die member 116 and raising the pressure plate off the strip of material 100.

Fixedly mounted within the casing, on the platform 65, at the end of the machine opposite the punch 99, there is a bracket 169, see Figs. 4 and 9, which has a wall 170 extended at right angles to the bracket 169. Mounted on the wall 170, by means of nut and bolt assemblies 171 there is a block 172. The block 172 is formed with a vertical cutout 173, see Figs. 4, 5 and 12, closed by the wall 170 and which forms a vertical passage through which the belt 174 being formed passes to discharge through an appropriately located hole 175 formed in the platform 65, see Fig. 5. The bracket 169 is secured in position on the platform 65 by several bolts 176.

To support the belt 174 in a proper elevated position to receive a further link 152, a pressure foot 177 has a portion slidably mounted in an appropriate guideway 172^a formed in the top portion of the block 172. Attached to the block 172, on the side opposite the wall 170, there is a U-shaped bracket 178. The bracket 178 is secured in position by the same nut and bolt assemblies 171 which secure the block 172 to the wall 170. A thumb screw 179 is threaded through the bracket 178 and is formed with a reduced inner portion, see Fig. 5, which extends into the adjacent end of an expansion spring 180. The other end of the expansion spring 180 is extended into a complementary recess formed in the portion of the pressure foot 177 which slidably engages the guideway 172^a formed in the block 172. A lock

nut 181 is threadedly engaged on the thumb screw 179 to be tightened against the adjacent face of the U-shaped bracket 178 for locking the thumb screw 179 in a proper adjusted position to control the tension on the spring 180. The spring 180 should exert a sufficient pressure to clamp the belt 174 against the adjacent face of the wall 170, as shown in Fig. 5, to hold the top of the belt with the proper slots of the links 152 aligned with the link feeding mechanism to have the link 152 engaged therewith, this is the position shown in Fig. 5. However, the spring 180 should not exert such pressure as to prevent the belt 174 from being drawn downward when required following each insertion of a link 152.

The link feeding mechanism, previously referred to, is characterized by a pilot 182 and a feeder 183. The feeder 183 moves more slowly than the pilot 182 and actually carries the link which is to be added to the belt and the pilot 182 enters the slots of the links of the belt prior to the feeder and guides the link, to be added, into position.

The pilot 182 is formed of flexible metallic material and has a horizontal portion extended parallel to the feeder 183 and a vertical portion secured to a pilot carrier 184, by means of a nut and bolt assembly 185, see particularly Fig. 5. The pilot carrier 184 is slidably mounted on rods 186 which are supported at their ends in brackets 187 secured to the top wall 61 of the casing by means of bolts 188. Extended toward the punch 99 from the pilot carrier 184, there is a transfer 189 for conveying each completed link from the punch 99 to the feeder 183. The transfer 189 is comprised of a transfer arm 190 which is secured to the pilot carrier 184, at one of its ends, by a screw 191. The free end of the transfer arm 190 pivotally supports a transfer member 192 which has a downwardly extended finger portion 193 extended away from the punch 99.

As the pilot carrier 184 moves on the rods 186 toward the punch 99, the finger portion 193 will contact the free end of the head portion 153 of the link 152 which is to be completed pivoting the transfer member 192 upward so that the free end of the finger portion 193 can ride across the top face of the link as the pilot carrier 184 completes its movement toward the punch 99. Prior to the time that the pilot carrier 184 starts its motion away from the punch 99, the action of the punch will complete that foremost link 152 freeing that link to be carried by the transfer to the feeder 183, which will be in the position shown in Fig. 5. When the pilot carrier 184 starts its motion away from the punch 99, the transfer member 192 will pivot downward, due to the action of gravity, causing the free end of the finger portion 193 to grip the top face of the completed foremost link 152 and carry it to a position over the top of the feeder 183.

The feeder 183 is formed of a strip of metal and has its top face formed with three spaced ratchet teeth 194 spaced from each other a distance equal to the spacing of the slots 156, 157 and 158 formed in the links 152. When the transfer 189 carries the completed link 152 to a position over the feeder 183 in which the slots 156, 157 and 158 are aligned with the teeth 194, those teeth will engage the slots so that the feeder 183 can now function to carry the completed link further. Up to this time, the movement of the feeder 183 has been slower than the rate of movement of the pilot 182, as will become clear as this specification proceeds, but now the rate of

11

movement of the feeder 183 begins to speed up so that eventually the feeder 183 catches up to the pilot 182. With this increased movement and since the teeth 194 of the feeder 183 are engaged with the slots 156, 157 and 158 of the completed link 152, the link will begin to move away from the free end of the finger portion of the transfer member 192. As such movement of the completed link 152 is in the direction in which the transfer member 192 is free to pivot relative to its transfer arm 190, the completed link 152 will merely slide beneath the free end of the finger portion 183.

The feeder 183 is fixedly mounted on a cross head 195 which is slidably mounted on the top wall 61 of the casing for movement to and fro between the punch 99 and the belt 174 being formed by the machine. The cross head 195 is slidably supported in a complementary slot 196 formed in the top wall 61 of the casing.

Means operated by rotation of the cam disc 90 is provided for oscillating the feeder 183 and the pilot 182 to and fro between the punch 99 and the belt 174 being formed by the machine and in proper timed relation with respect to each other. This means comprises a crank pin 197, see Figs. 4, 6 and 8, which extends vertically from the top face of the crank disc 90 within the top cam surface 147. The crank pin 197 is non-rotatively anchored within a complementary opening 198 formed in the top of the crank disc 90. An arm 199 is rotatively engaged on the bottom portion of the crank pin 197 and at its free end rotatively supports a vertical pivot pin 200. The top end of the pivot pin 200 passes freely through a complementary elongated slot 201 formed in the top wall 61 of the casing. The front of the pilot carrier 184 is formed with an integral forwardly extending lug 202 formed with an opening through which a reduced threaded top portion 203 of the pivot pin 200 extends. A nut 204 is threaded onto the reduced threaded top portion 203 and clamps the lug against the shoulder of the pivot pin 200 at the base of the reduced portion 203 for securely connecting the pilot carrier 184 to the pivot pin 200. Thus, as the cam disc 90 rotates, the pilot carrier 184 together with the pilot 182 will be caused to oscillate to and fro on the rods 186.

The means for oscillating the feeder 183 also operates off the crank pin 197 and comprises an arm 205 which projects radially from the top end of the crank pin 197. The arm 205 is secured to the top end of the crank pin 197 by means of a pin 206, see Fig. 4, engaged through those parts. The outer end of the arm 205 rotatively supports a peg 208, see Fig. 8, which depends from a block 207. The block 207 is formed with a passage which extends therethrough at right angles to the peg 208 and through which the intermediate portion of a rod 208 slidably extends. One end of the rod 208 is anchored in a recess formed in a block 209, by means of a pin 210. The block 209 is formed with a vertical passage into which a pivot peg 211 extends. The pivot peg 211 depends from the cross head 195 upon which the feeder 183 is mounted.

The other end of the rod 208 is slidably extended through a passage 212 formed in a block 213. Upstanding from the block 213, there is a pivot peg 214. The top of the pivot peg 214 extends freely through an enlarged opening 215 formed in the top wall 61 of the casing. Resting on the top face of the top wall 61 there is a rectangular plate 216 of a size greater than the

12

size of the enlarged opening 215 so that the plate cannot fall through the opening 215. The plate 216 is formed with a circular opening 217 through which the top end of the pivot peg 214 rotatively extends. The top end of the pivot peg 214 is sleeved by a ring 218 which turnably rests on the top face of the pivot peg 214. A pin 219 is engaged through the ring 218 and the top end of the pivot peg 214 securing the pivot peg 214 in position for rotation relative to the rectangular plate 216.

The arm 205 is secured to the crank pin 197 by the peg 206 so that the arm 205 is substantially forty-five degrees behind the arm 199 when the parts are in the position shown on the drawings; i. e. when the pilot 182 and the feeder 183 are at the ends of their strokes closely adjacent the punch 99. With this relationship between the arms 199 and 205, when movement of the pilot 182 and the feeder 183 starts towards the belt 174, being formed in the machine, the pilot 182 will initially move more rapidly than the feeder 183 and will reach the belt 174 well in advance of the feeder. However, as the pilot 182 approaches the end of its movement toward the belt 174, movement of the feeder 183 will be speeded up to the point where the feeder 183 catches up with the pilot, this can be understood from Figs. 34 to 49 which diagrammatically illustrate the relationships between the pilot 182 and the feeder 183 during their movements between the punch 99 and the belt 174. On the return movement of the pilot 182 and the feeder 183 the reverse is true. The feeder 183 initially moves more rapidly and then slows down and the pilot initially moves more slowly and then speeds up to catch up with the feeder 183.

As previously indicated, the feeder 183 during its movement toward the belt 174, being formed, carries another link 152 which is to be added to the belt. As the feeder 183 approaches the end of its stroke toward the belt 174, the feeder 183 catches up with the pilot 182 so that the feeder 183 and the supported link 152 ride beneath the pilot 182, as shown in Figs. 42 and 43, until the feeder 183 completes its stroke when the feeder 183 and the link 152 are completely beneath the pilot 182, as shown in Figs. 44 and 45. From the disclosure on the drawings, it will be appreciated that the pilot 182 and the feeder 183 are of a width less than the link 152 and that the pilot and feeder engage the links mid-way between their widths.

Means is provided for adjusting the position of the rectangular plate 216 on the top face of the top wall 61 of the casing to control the length and/or the position of the stroke with relation to the punch 99 and the belt 174 being formed. This means is best illustrated in Figs. 7 and 22 and comprises a hollow cap 220 which is engaged over the top end of the pivot peg 214 and the rectangular plate 216. Diametrically opposite sides of the hollow cap 220 are formed with outwardly extending flanges 221 which are secured to the top wall 61 on opposite sides of the opening 215 by means of bolts 222. The cap 220 has depending side walls which extend along the adjacent sides of the plate 216 but which are spaced therefrom, as shown in Fig. 22. To control the length of the stroke of the pilot carrier 184 and to control the length of the stroke of the pilot 183, between the punch 99 and the belt 174 being formed, the front and rear side walls of the cap 220 have threaded therethrough a pair of bolts 223 which have their inner ends abutting the

sides of the plate 216. Lock nuts 224 are threaded onto the shanks of the bolts 223 and tightened against the sides of the cap 220 for holding the bolts 223 in a desired position. As the bolts 223 are adjusted, the plate 216 and the block 213 supported by the plate will be moved forward or rearward relative to the block 209 varying the spacing between those blocks to shorten or lengthen the stroke of the pilot carrier 184.

Likewise, to properly position the ends of the stroke of the pilot carrier 184 with relation to the punch 99 and the belt 174, being formed, there is a pair of bolts 225 threaded through the end side walls of the cap 220, at right angles to the bolts 223, and which have their inner ends abutting the adjacent sides of the plate 216. Lock nuts 226 are threaded on the shanks of the bolts 225 and tightened against the adjacent faces of the respective end side walls of the cap 220 for holding the bolts 225 in their desired adjusted position. As the bolts 225 are adjusted the plate 216 and the block 213 supported by the plate will be moved to the right or the left to pivot the rod 208 about the peg 206 as a fulcrum to reversely move the block 209 to the right or the left to properly position the stroke of the pilot carrier 184 with relation to the punch 99 and the belt 174, being formed, without effecting the length of the stroke. Adjustments of the bolts 223 vary the length of the stroke of the pilot carrier 184 without effecting the positioning of the stroke.

The previously referred to means for periodically turning the driven roller 110 to cause the rollers 110 and 111 to rotate and feed the strip of material 100 toward the punch 99, is best shown in Figs. 1 to 4 and 6, and is operated by oscillation of the pilot carrier 184 on the rods 186. As clearly shown in Fig. 1, the turning means includes an L-shaped member 497 having one arm rotatively supported on the shaft 108 forwardly of the adjacent arm 107. The L-shaped member 497 is rotatively retained in position on the shaft 108 by a collar 498 which is fixedly secured to the forwardly extending end of the shaft 108. The other arm of the L-shaped member 497 is extended vertically and has pivotally attached to the upper end thereof, by means of a pin 499, one end of a rod 500. The free end of the rod 500 is slidably extended through a lug 501 integrally formed with one of the brackets 187 which supports the rods 186. That free end of the rod 500 carries an upstanding projection 502 which engages the pilot carrier 184, as clearly shown in Fig. 6.

A pin 503 pivotally supports a gripper 504 upon the L-shaped member 497 above the collar 498. The length of the gripper is somewhat longer than the space between the pin 503 and the top surface of the collar 498 so that the gripper 504 depends under the influence of gravity in the position shown in Fig. 1, to rest against the collar 498. A contraction spring 505 operates between a pin 506 mounted on the L-shaped member 497 and a pin 507 mounted on the adjacent arm 107.

The contraction spring 505 functions to turn the L-shaped member 497 into a position in which the rod 500 will be urged into a position in which the projection 502 will be abutted against the pilot carrier 184. As the pilot carrier 184 starts its movement away from the punch 99, the L-shaped member 497 will be turned by the spring 505 jamming the free end of the gripper 504 against the collar 498. This will cause the collar 498, the shaft 108 and the driven roller 110 to be turned. Due to the geared en-

agement of the idler roller 111 with the driven roller 110, the idler roller will also be turned to advance the end of the strip of material 100 through the punch 99. At the time that the strip of material 100 is being advanced, the cam disc 90 will be in a turned position in which the movable die member 124 will be in a raised position off the fixed die member 116. On the return movement of the pilot carrier 184, the rod 500 will be pushed against the action of the spring 505 to pivot the L-shaped member 497 back to its starting position and during this return movement the free end of the gripper 504 will merely slide over the periphery of the collar 498 without turning the same.

Curling means are provided for the purpose of curling in the sides of the head portion 153 of the link 152 being fed toward the belt 174 being formed, so that the head portion of the link can be drawn through the aligned slots of the belt by the feeder 183. The curling means is characterized by a pair of curling arms 227 pivotally supported at their outer ends on the top wall 61 of the casing by means of pivot pins 228. The free ends of the curling arms 227 are formed with curling members 229 which are directed toward each other and which are formed at their inner ends with curling grooves 230, shown most clearly in Figs. 38 and 39. The free ends of the curling arms 227 are provided with upstanding rollers 231 which are engaged between curling cams 232 which extend toward the rollers 231 from the pilot carrier 184. The rollers 231 are retained in contact with the curling cams 232 by means of an expansion spring 233 which has its ends attached to the free ends of pins 234 which extend from the pivotally attached ends of the curling arms 227. The curling cams 232 are of a length so that the rollers 231 will be in engagement with the cams in all of the shifted positions of the pilot carrier 184.

As the pilot carrier 184 approaches the end of its stroke, see Fig. 38, the curling cams 232 will function to pivot the curling arms 227, against the action of the spring 233 to position the curling members 229 with their curling grooves 230, as shown in Fig. 40. Thus, when the feeder 183, carrying the link 152 which is to be added to the belt 174, being formed, approaches the end of its stroke, the rounded head portion 153 of the link will be fed into the curling grooves 230 of the curling members 229. The curling grooves 230 will then function to curl the sides of the rounded head portion 153 in position over the top of the pilot 182, as shown in Figs. 42 and 44, reducing the width of the head portion to the length of the aligned slots in the belt 174 so that the head portion can be forced through those aligned slots of the belt to the position shown in Fig. 46. As the pilot carrier 184 starts its return movement the curling cams 232 will move away from the curling arms 227 freeing the arms to be returned to their starting position, as shown in Fig. 48, by the spring 233 so that the curling members 229 will be moved clear of the body portion 155 of the link 152 leaving the link free to be folded about the neck portion 154 by the downward movement of the belt 174, to be explained hereinafter.

Means is provided on the side of the belt 174 opposed to the side where the curling members 229 are located, for again straightening out and flattening the rounded head portion 153 of the link 152 after it has been fed through the aligned slots of the belt. This means is comprised of a

pair of spaced vertically arranged bars 235 which are vertically slidably extended through the U-shaped bracket 178. The bars 235 are spaced to provide clearance for the projecting portion of the pressure foot 177 and related parts, as shown in Figs. 4 and 5. Disposed between the top ends of the bars 235 there is a block 236 which is secured in position by several nut and bolt assemblies 237. Extended across the bottom ends of the bars 235 there is a pin 238 having a reduced threaded portion 238a projecting through complementary openings formed in the bottom ends of the bars 235 and an enlarged portion 238b extended laterally from one side of the respective bar 235 for a purpose which will become clear as this specification proceeds. Mounted on the reduced threaded portion 238a between the adjacent faces of the bars 235 there is a bushing 239, see Fig. 12, which has a length corresponding to the thickness of the block 236 to cooperate with the block 236 in equally spacing the bars 235 throughout their length. A nut 240 is threaded onto the free end of the reduced threaded portion 238a of the pin 238 and against the adjacent face of the respective bar 235 for securing the pin 238 in position.

An uncurling head 241 is formed with a reduced portion which is engaged between the adjacent faces of the bars 235 immediately below the block 236, as shown in Fig. 5. The head 241 is secured in position by means of a flat plate 242 which extends vertically along the bars 235 on the side opposite the side from which the head extends. Several bolts 243 are passed freely through openings formed in the plate 242 and are threaded into complementary openings formed in the reduced portion of the uncurling head 241 for clamping the curling head and the plate in position when the bolts 243 are tightened into position.

The bottom face of the uncurling head 241 is formed, facing the belt 174, with a pair of uncurling surfaces 244 which extend away from each other and from an apex 245 located at the longitudinal center line of the belt 174. During the time that the link 152 is being fed through the aligned slots of the belt 174, the bottom face of the uncurling head 241 will be in a position raised just slightly off a floating plate 246, as shown in Figs. 39, 41, 43, 45, 47 and 49. This spacing will permit the free end of the rounded head portion 153 of the link 152 to pass between the adjacent faces of the uncurling head 241 and the floating plate 246 so that the curled sides of the rounded head portion 153 will contact the uncurling surfaces 244 of the uncurling head 241 after passing through the aligned slots and be straightened out thereby.

The floating plate 246 slidably rests on the top face of the block 172 between the adjacent faces of the bars 235 with its top face aligned with the bottom edges of the aligned slots of the belt 174 through which the rounded head portion 153 of the link 152 is being passed. Downward movement of the belt 174 for folding each added link 152 in half about the reduced neck portion 154 causes the floating plate 246 to be pushed outward. When the uncurling head 241 is being moved downward, the bottom edge of the flat plate 242 is formed with a beveled surface 247 which engages a complementary beveled surface 248 formed along the outer edge of the floating plate 246. This contacting of the beveled surfaces 247 and 248 causes the plate 246 to be pushed inward to back up the belt 174, as shown

in Figs. 39, 41, 43, 45, 47 and 49, and prevent flexing thereof during the time that the rounded head portion 153 of the link 152 is being passed through the aligned slots of the belt.

A contraction spring 249, see Figs. 5 and 6, operates between a pin 249 which projects from one of the bars 235 and a lug 250 mounted on the platform 85. The spring 249 functions to continuously urge the bars 235 and the uncurling head 241 carried thereby into a lowered position. Means controlled by rotation of the cam disc 90 is provided for controlling upward movement of the bars 235 against the action of the contraction spring 249. The upward movement controlling means is comprised of an arm 251, see Figs. 4, 6, 8 and 12, which is provided at one end with a roller 252 which rolls on a cam surface 253 formed on the bottom face of the cam disc 90. The other end of the arm 251 is engaged beneath the enlarged portion 238b of the pin 238, as clearly shown in Fig. 12. The arm 251 is pivoted, closely adjacent the roller 252, on a boss 254 by means of a pivot bolt 255.

Details of the cam surface 253 are given in Fig. 26, from which it will be noted that the cam surface is comprised of an intermediate surface 256, a deeper cut surface 257 and a shallower cut surface 258 formed about the bottom face of the cam disc 90. The surfaces 256, 257 and 258 are connected at their adjacent ends by inclined surfaces 259 so that the roller 252 may conveniently pass from one surface to the other.

In the fully raised position of the bars 235 and the uncurling head 241, as shown in Figs. 5, 36 and 37, the roller 252 will be riding on the shallower cut surface 258 of the cam surface 253. As the feeder 182 approaches the aligned slots of the belt 174, as shown in Figs. 38 and 39, the roller 252 will have ridden off the shallower cut surface 258 down the respective inclined surface 259 and onto the intermediate surface 256. This immediately frees the bars 235 and the uncurling head 241 to be pulled downward by the contraction spring 249 to space the bottom face of the uncurling head 241 slightly above the top face of the floating plate 246. That downward movement caused the beveled surface 247 of the plate 242 to ride over the complementary beveled surface 248 of the floating plate 246 and push inward thereon to back up the belt 174 as previously described.

As the intermediate surface 256 is the longer of the three surfaces comprising the cam surface 253, the bottom face of the uncurling head 241 will be supported in its position just slightly above the floating plate 246 all the time that the end of the pilot 182 is extended through the aligned slots of the belt and during the time that the feeder 182 is slipping the curled rounded head portion 153 through the aligned slots of the belt 174. In this position, the uncurling surfaces 244 of the uncurling head 241 function to uncurl the sides of the rounded head portion 153 after it has been completely passed through the aligned slots 65 of the belt 174. However, the moment the end of the pilot 182 is completely withdrawn from the aligned slots of the belt 174, as shown in Figs. 46 and 47, the roller 252 moves off the intermediate surface 256 down the respective inclined surface 259 and onto the deeper cut surface 257, freeing the bars 235 and the uncurling head 241, carried by the bars 235, to be lowered still further by the spring 249 until the bottom face of the uncurling head 241 just frictionally touches the top face of the rounded head portion 153 of

the inserted link 152, as shown in Figs. 47 and 49. During this time, the feeder 183 is retracted from the aligned slots of the belt 174 with the frictional contact between the uncurling head 241 and the rounded head portion 153 retaining the link 152 against possible withdrawal from the aligned slots of the belt. As the feeder 183 is completely withdrawn from the aligned slots of the belt 174, the roller 252 rides off the deeper cut surface 257 along the respective inclined surface 259 and back onto the shallower cut surface 258 again raising the bars 235 and the uncurling head 241, against the action of the spring 248, to the fully raised position shown in Figs. 34 and 35. This action frees the inserted link 152 to be folded in half as the belt 174 is moved downward and also frees the floating plate 246 to move out of contact the belt 174 so that the link 152 may fold in half without obstruction.

Below the pressure foot 177, the completed portion of the belt 174 passes between a feed roll 260 and an idler roll 261, see Figs. 5, 6 and 12. The feed roll 260 is fixedly attached to a drive shaft 262 by means of a pin 263, see especially Fig. 8. The drive shaft 262 is rotatively supported in a bracket 264 attached to the wall 170 by several nut and bolt assemblies 265, see Fig. 6. The idler roll 261 is freely rotatively mounted on an intermediate portion of a shaft 266 which has its ends fixedly supported in blocks 267. Rods 268 extend outwardly from the blocks 267 and are slidably passed through complementary holes formed in spaced depending lugs 269 formed on the block 172. Expansion springs 270 are coaxially wound on the rods 268 and operate between the blocks 267 and the lugs 269 urging the rods 268 into positions in which the completed belt 174 will be frictionally gripped between the feed roll 260 and the idler roll 261.

Means operated by the cam disc 90 is provided for rotating the feed roll 260 just slightly following each addition of a link 152 to move the belt 174 downward the required distance to fold the added link 152 in half and to bring the next set of aligned slots of the belt into proper alignment with the pilot 182 and the feeder 183 for the addition of the next link.

The means for rotating the feed roll 260 includes a gear 271 integrally formed along one side of the feed roll 260 concentric therewith, see Fig. 8. The gear 271 in turn meshes with a second gear 272 which is rotatively supported on a shaft 273. The shaft 273 is turnably supported in a bearing 274 supported by an extension of the bracket 264 which rotatively supports the drive shaft 262. Fixedly secured to the end of the shaft 273 on one side of the gear 272 there is an arm 275 which has a roller 276 projecting laterally from one side thereof to roll on the top cam surface 147 of the cam disc 90. Also fixedly mounted on the shaft 273, on the other side of the gear 272 there is an upstanding arm 277. Pivotedly attached to the upper end of the arm 277, by means of a pivot pin 278 there is a gravity actuated pawl 279 which engages the gear 272. Thus, as the arm 275 is moved downward, the shaft 273 will be rotated turning the arm 277 and causing the pawl 279 to turn the gear 272 which will correspondingly turn the gear 271 and turn the feed roll 260 to move the belt 174 downward.

The free end of the arm 275 has attached thereto the upper end of a contraction spring 280, see Figs. 4, 5 and 10, which in turn has its bottom end attached to a lug 281 which projects from the platform 65. The spring 280 functions

to pivot the arm 275 downward when the roller 276 rolls off the raised portion 148 onto the lowered portion 149 of the top cam surface 147 of the cam disc 90. A stop is provided for limiting downward pivoting of the arm 275 when the roller 276 is rolling on the lower portion 149 of the top cam surface 147. This stop is required as the lower portion 149 is considerably deeper than it is required to move the arm 275 downward for the purpose of advancing the belt 174 the required amount.

The stop is characterized by a vertical post 282 which has its bottom end threaded through the platform 65. A lock nut 283 is threaded onto the post 282 to be tightened against the top face of the platform 65 for securing the post in a desired vertically adjusted position. The top end of the post 282 is formed with an enlarged head 284 which is to be contacted by a pin 285 which extends laterally from the side of the arm 275. When the free end of the pin 285 rests on the top face of the head 284, the arm 275 will be retained against further downward pivoting under the influence of the spring 280 when the deepest part of the lower portion 149 of the cam surface 147 passes beneath the roller 276. As rotation of the cam disc 90 continues and the inclined surface at the opposite side of the lower portion 149 approaches the roller 276 the roller will roll up that inclined surface onto the raised portion 148 of the top cam surface 147, raising the arm 275 against the action of the spring 280 and lifting the pin 285 off the head 284. On this reverse movement of the arm 275, the arm 277 will be turned with the shaft 273 causing the pawl 279 to merely idle over the teeth of the gear 272. As the gear 272 is rotatively mounted on the shaft 273 it will be retained against rotation by the drag created by the gear 271 and the feed roll 260 which engages the belt 174.

Manually controllable mechanism is provided for controlling the number of links 152 which may be added to each belt 174 so as to permit belts of different lengths to be formed by the present machine. This manually controllable mechanism is comprised of a substantially U-shaped bracket 286, see Figs. 4, 5 and 8 to 10, which is secured to the inside face of the platform 65 by several screws 287. Slidably and rotatively extended through the upstanding arms of the U-shaped bracket 286 there is a shaft 288 composed of an inner section 288^a and an outer section 288^b. Fixedly mounted on the outer end of the inner section 288^a there is a dial plate 289 having a hub portion 289^a facing the outer side of the casing. The outer shaft section 288^b is formed at its inner end with a hub portion 290 which is releasably secured to the hub portion 289^a of the dial plate 289 by several screws 291. The free end of the outer shaft section 288^b is rotatively and slidably extended through a complementary hole formed in the plate 72. Above the projected end of the outer shaft section 288^b the plate 72 is formed with a window opening 292 and the face of the dial plate 289 adjacent the plate 72, is imprinted adjacent its periphery with a plurality of numbers 293 arranged in chronological order to be successively seen through the window opening 292, as seen in Fig. 11. The free outer end of the outer shaft section 288^b has mounted thereon by means of a set screw 294, a control knob 295. By means of the control knob 295, the shaft 288 can be axially moved inward, for a purpose which will become clear as this specification proceeds, and/or rotated for the purpose of aligning a desired num-

ber 293 on the dial plate 289 with the window opening 292.

Freely rotatively mounted on the inner shaft section 288^a, between the upstanding arms of the U-shaped bracket 286, there is a circular disc 296 which is formed about its periphery with a plurality of ratchet teeth 297—there being one ratchet tooth 297 for each of the numbers 293 on the dial plate 289. Fixedly mounted on the inner shaft section 288^a between the upstanding arms of the U-shaped bracket 286, there is a control detent 298. The control detent 298 is shown in detail in Fig. 23 from which it will be noted that the outer end of the detent 298 is formed with a laterally extending pin 299 which is selectively engageable with one of a plurality of complementary holes 300 formed in the adjacent upstanding arm of the U-shaped bracket 286. The holes 300 correspond in number to the number of teeth 297 on the periphery of the circular disc 296 and to the number of numbers 293 on the dial plate 289. The holes 300 are arranged in a circle which is concentric with the shaft 288.

Disposed between the adjacent faces of the circular disc 296 and the detent 298 there is a coil spring 301 coaxially wound on the shaft 288. One end of the spring 301 engages a complementary hole in the circular disc 296 and the other end of the spring engages a complementary hole in the detent 298, as shown in Fig. 10. The spring 301 functions to retain the circular disc 296 in facial contact with the adjacent upstanding arm of the U-shaped bracket 286 in all of the axially shifted positions of the shaft 288 and further acts to retain the shaft 288 in an axial shifted position, due to its fixed connection with the control detent 298, in which the control detent will be in facial contact with its adjacent face of the upstanding arm of the U-shaped bracket 286 and in which the pin 299 of the detent will be engaged into one of the holes 300 of that adjacent upstanding arm of the U-shaped bracket. In addition, the spring 301 is under a slight normal load tending to retain the circular disc 296 in a turned position in which a stop pin 302 will be engaged against the control detent 298. The stop pin 302 extends from either side of the circular disc 296 radially outward from the shaft 288, as shown in Fig. 10. The end of the stop pin 302, opposed to the end which is to engage the control detent 298, will engage a projecting end of a lug 303 fixedly mounted on a rotatively supported shaft 304 to cause the shaft 304 to be pivoted slightly for a purpose to be explained hereinafter.

When the one end of the pin 302 engages the free end of the lug 303 and the opposite end of the pin 302 is engaged by the end of the control detent that is the "zero" position of the machine and the "0" numeral 293 of the dial plate 289 will be displayed in the window opening 292. To set the machine, to produce belts having twenty interengaged links 152, the control knob 295 is pressed inward moving the shaft 288 axially against the action of the spring 301 and the control detent 298 away from its respective upstanding arm of the U-shaped bracket 286 disengaging the pin 299 from the hole 300 with which it was engaged. With the control knob 295 pressed inward the shaft 288 is free to be rotated in the proper direction to bring the numeral "20" imprinted on the dial plate 289 into view in the window opening 292, as shown in Fig. 11. When the control knob 295 is then released, the spring 301 will immediately function to urge the shaft 288 axially outward carrying the control detent 78

298 therewith and engaging the pin 299 of the control detent 298 into the hole 300 with which it became aligned as a result of the turning of the shaft 288 and the control detent 298. During the time that the shaft 288 was being turned the tension on the spring 301 was acting to correspondingly turn the circular disc 296 so that the pin 302 moved away from the lug 303 but retained its engagement with the control detent 298.

10 Means controlled by up and down movement of the arm 275 is provided for advancing the circular disc 296 one ratchet tooth 297 each time a link 152 is added to the belt 174. This movement is effected in opposition to the action of the spring 15 301, so that the pin 302 will be moved away from the control detent 298 and toward the lug 303. This means comprises a radial arm 305 mounted on the shaft 273 on the side of the bearing 274 opposed to the side on which the arm 277 is mounted. Pivotaly mounted on the upper end of the radial arm 305 there is mounted a pawl 306 which will advance the circular disc 296 one tooth each time the arm 275 pivots downward. When the arm 275 is again moved upward the 20 free end of the pawl 306 will idle over the tooth of the circular disc 296. The pawl 306 functions under the action of gravity.

To restrain the circular disc 296 against turning back when the pawl 306 is idling over the 30 tooth 297 of the disc, there is provided a stop pawl 307 which is pivotally mounted on one of the upstanding side arms of the U-shaped bracket 286 by means of a pivot pin 308. When the pawl 306 is moved to advance the circular disc 296 a 35 distance equal to one ratchet tooth 297, one of the ratchet teeth will slip beneath the gravity actuated stop pawl 307. On the reverse movement of the pawl 306, the stop pawl 307 will be engaged with one of the teeth 297 of the circular 40 disc 296 and hold the disc against turning back under the influence of the spring 301.

When the final link 152 has been added to the 45 belt 174, the circular disc 296 will be turned to its position in which the pin 302 will strike the lug 303 and turn the shaft 304 to cause the machine to be momentarily stopped, to free the completed belt 174 to drop through the hole 175 in the platform 65 and other related operations to 50 condition the machine for the start of another belt. The mechanism effected by turning of the shaft 304, includes a bar 309 which is supported for vertical sliding movement alongside of a vertical bracket 310 by several clamps 311. The bottom end of the bracket 310 is fixedly mounted on the platform 65 and the clamps 311 are secured to the bracket 310 by several nut and bolt assemblies 312. The bar 309 is urged downward by a 55 spring 313, see Fig. 7, which has its upper end bearing against the bottom face of the top wall 61 of the casing and its bottom end seated in a recess 314, see Fig. 4, formed in the top end of the bar 309.

An extension 315 projects laterally from the 60 bar 309 through a vertical slot 316 formed in the bracket 310 and has rotatively mounted on its free end a roller 317. The roller 317 rolls on the top cam surface 147 of the cam disc 90. When the roller 317 is rolling on the raised portion 148 of the top cam surface 147, the bar 309 will be 65 lifted against the action of the spring 313. However, when the roller 317 rolls onto the lower portion 149 of the top cam surface 147, the bar 309 will be free to be urged downward by the spring 70 313.

The forward end of the shaft 304 is rotatively

supported in a bracket 318 which extends up from the platform 65 and carries a detent 319. Similarly, the bar 309, between the clamps 311, has pivotally mounted thereon a lever 320. The lever 320 is pivotally supported on the bar 309 by means of a pin 321, see Fig. 7, which is so located that the major portion of the weight of the lever will be on the side of the pin adjacent the detent 319. Thus, by the action of gravity this distribution of weight will cause the lever 320 to assume a pivoted position in which a leaf spring 321 carried by the lever will be resting against the free end of the detent 319, as shown in Fig. 7. The side of the lever 320 opposed to the side mounting the leaf spring 321 is formed with a shoulder 323.

A bracket 324 extends upward from the platform 65 and intermediate of its height it carries a pivotally mounted link 325. The link 325 is pivoted intermediate of its ends on the bracket 324 by means of a pin 326. One end of the link 325 is positioned adjacent the shouldered side of the lever 320 and is formed with a depending pointed portion 327 to be engaged by the shoulder 323 of the lever 320 when the lever is pivoted into a vertical position for in turn pivoting the link 325 about the pin 326.

The opposite end of the link 325 is pivotally connected to the upper end of a vertical bar 328. The free end of the vertical bar 328 is extended downward through a complementary hole formed in the platform 65 and is associated with mechanism for separating the clutch discs 82 and 85 to stop rotation of the cam disc 90. Details of the mechanism for separating the clutch discs 82 and 85 are illustrated in Figs. 6 to 8 and 13 and comprises a thrust bearing having an inner race 329 which is fixedly secured to the tubular shaft 80 which carries the clutch disc 82, by several collars 330 and 331 which are threadedly engaged upon a sleeve 344 which is rotatively and slightly vertically slidably mounted on the tubular shaft 80. The thrust bearing further includes an outer race 332 with the usual balls 333 between the races 329 and 332. The outer race 332 is the stationary race and has fixedly secured thereto a collar 334 formed with four radially outwardly projecting lugs 334^a, see Fig. 13. The lugs 334^a are formed with holes through which the tie rods 94 extend for guiding vertical sliding of the collar 334 and in turn the thrust bearing and the tubular shaft 80 and the clutch plate 84 carried thereby.

Extended laterally from diametrically opposite sides of the collar 334 there are bosses 335 which continue at their free ends into laterally extending trunnions 336. Links 337 extended along the sides of the collar 334 each have one end pivotally attached to one of the trunnions 336. The other ends of the links 337 are fixedly attached to the ends of a shaft 338. The intermediate portion of the shaft 338 is slidably extended through a tubular bearing 339, see Figs. 6 and 13, formed on one of the upstanding arms of the U-shaped bracket 78. The other arm of the U-shaped bracket 78 is formed with a similar bearing 340 which is not used. The links 337 which have a slight play in their connection with the trunnions function to insure level up and down movement of the collar 334 without binding action on the vertical tie rods 94.

The bottom end of the vertical bar 328 is mounted on one of the trunnions 336, as shown in Figs. 7, 8 and 13. The vertical bar 328 is urged into a raised position by a contraction spring 341, see Figs. 7 and 8, which has one end connected to

a lug 342 which depends from the bottom face of the platform 65. The other end of the spring 341 is connected to a pin 343 which projects from the bar 328.

When the pin 322 strikes the lug 303, following the addition of the last link 152 to the belt 174, the shaft 304 will turn causing the detent 319 to be turned to flex the leaf spring 322 loading the same causing the lever 320 to bear against the pointed portion 327 of the pivotally mounted link 325. Rotation of the cam disc 90 will continue until the roller 317 rolls into the lower portion 149 of the top cam surface 147. Immediately, the tension on the leaf spring 322 will pivot the lever 320 into a vertical position when the shoulder 323 clears the pointed portion 327 of the link 325. The pivoted detent 319 will retain the lever 320 in its vertical position and the shoulder 323 will be immediately below the pointed portion 327. As the roller 317 rolls off the lower portion 149 onto the raised portion 148 of the top cam surface 147, with further rotation of the cam disc 90, the lever 320 will be raised in its vertical position causing the shoulder 323 to engage the pointed portion 327 pivoting the link 325 and causing the bar 328 to be urged downward against the action of the spring 341. This downward movement of the bar 328 will urge the collar 334 downward and also move the tubular shaft 80 downward against the action of the spring 91. This will immediately separate the clutch discs 82 and 85 arresting further rotation of the cam disc 90. The pointed portion 327 will retain its position seated on the shoulder 323 until mechanism hereinafter to be described pivots the lever 320 against the retaining action of the leaf spring 322.

The link 325 is mounted on the pivot pin 326 on one side of the bracket 324 and a radial arm 325^a is fixedly mounted on the pin on the opposite side of the bracket 324 for operating a brake to arrest the cam disc 90 against further rotation under the influence of inertia, which would disturb the synchronization of the various parts of the machine. The brake is comprised of a brake band 345 of metal, see Figs. 4 and 6 to 8, engaged about the cam disc 90 between the cam surfaces 147 and 253. The inside face of the band 345 has attached thereto a length of friction material 346, as clearly shown in Fig. 6.

Adjacent one side of the cam disc 90, there is provided a brake control member 347 composed of vertically spaced triangular plates 348 having vertical pins 349, 350 and 351 extended between the adjacent faces of the plates. The pin 349 forms the means for pivotally mounting the brake control member 347 upon the top end of a post 352 which extends vertically from the platform 65. Also, attached to the pin 349 between the adjacent faces of the plates 348 there is one end of the brake band 345.

Turnably supported on the pin 350 between the adjacent faces of the plates 348, there is a U-shaped member 353, see Figs. 4 and 8. The other end of the brake band 345 has a short rod 354 attached thereto at one end. The opposite end of the short rod 354 is threaded and passed through a complementary hole formed in the intermediate arm of the U-shaped member 353. Nuts 355 threadedly engage the threaded end of the short rod 354 on opposite sides of the intermediate arm of the U-shaped member 353, see Fig. 8, for adjusting the position of the brake band 345 with relation to the brake control member 347 so that the brake will properly grip the periphery of the

cam disc 90 when the control member 347 is pivoted about the pin 349.

A relatively weak coil spring 356 has one end attached to the pin 351 and its other end attached to a stationary part to be hereinafter referred to, for pivoting the brake control member 347 into a position in which the brake band 345 will be relaxed and the cam disc 90 will be free to be rotated. One end of a stronger coil spring 357 has one end attached to the pin 351 and its other end attached to the free end of the radial arm 325. When the link 325 is pivoted by the lever 320, the radial arm 325 will also be pivoted drawing on the stronger spring 357 which will overcome the weaker spring 356 and pivot the brake control member 347 to draw the brake band 345 tight about the cam disc 90 and instantaneously stop rotation thereof simultaneous with separation of the clutch discs 82 and 85.

Pivoting of the link 325 also operates mechanism to lift the pawls 306 and 307 to free the circular disc 296 to be turned back to its starting position, in which the pin 302 engages the control detent 298, by the tension on the spring 301. This means comprises a shaft 358 which is rotatively supported by the U-shaped bracket 286 and the bracket 318 above the shaft 304 and parallel thereto. As clearly shown in Fig. 6, the bottom face of the operating arm 138 of the punch mechanism is formed with a cutout 138a providing a clearance for the shafts 358 and 304.

The forward end of the shaft 358 has fixedly attached thereto a detent 359, see Fig. 7, which overlies, at its free end, a pin 360 which extends laterally from the side of the link 325 substantially above the pointed portion 321. Pivotal movement of the link 325 is transferred to turn the shaft 358 through the medium of the pin 360 and the detent 359. At its rear end, adjacent the U-shaped member 286, the shaft 358 has fixedly mounted thereon a radially extending link 361, see Figs. 4, 5 and 9. The free end of the link 361 is pivotally connected by means of a pin 362 to one end of another link 363 which in turn has its free end pivotally connected to an intermediate portion of a triangular segmental member 364, by means of a pin 365. The segmental member 364 is pivotally mounted on the end of the shaft 288 beyond the adjacent upstanding wall of the U-shaped bracket 286 and is pivotally retained in position on the shaft 288 by a collar 366, see Fig. 10, fixedly mounted on the end of the shaft. One side of the top portion of the segmental member 364 carries a laterally extending pin 367, see Figs. 4, 8 and 9, which lies beneath the pawl 306. The other side of the top portion of the segmental member 364 has secured thereto, by means of several screws 368, an arcuate extension member 369. The free end of the extension member 369 carries a projecting pin 370 which is normally positioned just in front of a beveled nose portion 307a formed on the free end of the stop pawl 307, see Fig. 9.

When the shaft 358 is turned, the links 361 and 363 will pull on the segmental member 364 and pivot that member causing the pins 367 and 370 to lift the pawls 306 and 307 clear of the ratchet teeth 297 of the circular disc 296. This raising of the pawls 306 and 307 frees the circular disc 296 to turn back to its starting position in which it rests against the side of the control detent 298, under the tension of the coil spring 301. The pawls 306 and 307 will be retained in their raised position all the time that the pointed portion 321 of the link 325 is resting on the shoulder 323 of

the lever 320. It is while the pawls 306 and 307 are in their raised position that the control handle 295 can be most conveniently manipulated for changing the position of the control detent 298 to adjust the machine to form belts of greater or less length than the belt just completed. If this manipulation is effected rapidly it can be completed before the cam disc 90 is released, as will be hereinafter described, for further rotation; however, it will be found more desirable to momentarily completely shut the machine off allowing more time to adjust the control detent 298. When the control detent 298 is properly adjusted the main source of power for the machine may again be turned on to pick up the cycle of the machine from where it left off. It is essential that the position of the control detent 298 be adjusted while the pawls 306 and 307 are in their raised position in order that the circular disc 296 will be free to adjust itself to the new position of the control detent under the influence of the coil spring 301.

Turning of the shaft 304, by the action of the pin 302 striking the lug 303, also sets in operation mechanism for raising the bars 235 an extra amount to move the pressure foot 171 away from the wall 170 a slight amount to free the finished belt 174 to drop through the hole 175 in the platform 65. Details of the bar raising mechanism is illustrated in Figs. 4, 7 and 12 and that mechanism comprises a link 371 which is pivotally connected at one end to the lower end of an arm 372 which extends radially from and is fixedly mounted on the end of the shaft 304 adjacent the detent 319. A pin 373 pivotally connects the end of the link 371 to the arm 372. The opposite end of the link 371 is pivotally connected to the short arm of a bell crank 374 by means of a pin 375. The bell crank is pivotally supported at the junction of its arms upon the platform 65 by means of a pivot pin 376, see Fig. 7. The other arm of the bell crank 374 is longer and has attached to the free end thereof one end of a strong expansion spring 377. The other end of the spring 377 is connected to a lever 378. More particularly, the end of the spring 377 is attached to a pin 379 which extends vertically from the lever 378 intermediate of its ends. The outer end of the lever 378 is pivotally attached to the platform 65 by means of a pin 380.

Slidably mounted on the enlarged portion 238b of the pin 238, between the arm 251 and the adjacent bar 235, there is a bushing 381. The end of the bushing 381, adjacent the arm 251, is beveled, as indicated at 381a in Fig. 12. The adjacent side of the arm 251 is formed with a complementary edge beveled portion 382, so that when the bushing 381 is shifted longitudinally on the enlarged end 238b of the pin 238 the bushing will be engaged between the adjacent faces of the enlarged end 238b and the arm 251. Upstanding from the free end of the lever 378 there is a long pin 383 which engages a circumferential groove 384 formed in the periphery of the bushing 381. A relatively weak spring 385 has one end connected to the pin 379 and its free end extended in the opposite direction from the strong spring 377 and connected to a pin 386 for holding the bushing 381, in the relaxed condition of the spring 377, in a position in which the bushing will be disengaged from between the adjacent faces of the pin 238 and the arm 251, as shown in Fig. 12.

As shown in Fig. 5, the outer end of the pressure foot 171 has mounted thereacross a pin 387.

25

The ends of the pin 387 project beyond the sides of the outer end of the pressure foot 177 and are extended into complementary slots 388 formed in the adjacent faces of the bars 235, see Fig. 12 also. The slots are alike in formation and each includes an upper vertical portion and a bottom inclined portion. During normal vertical movements of the bars 235, while links 152 are being added to the belt 174, the ends of the pin 387 are located within the vertical upper portions of the slots 388 so that the pressure foot 177 retains its position, under the influence of the spring 180, holding the belt 174 being formed again the wall 170, as shown in Fig. 5.

When the last link 152 is added to the belt 174 and the pin 302 of the circular disc 296 strikes the lug 303 turning the shaft 304, the arm 372 will be similarly turned pulling on the link 371 turning the bell crank 374 on its pivot pin 376. Movement of the bell crank 374 will draw on the stronger spring 377 tensioning it to pivot the lever 278 against the action of the weaker spring 385. This will slide the bushing 381 longitudinally on the enlarged portions 238^b of the pin 238 and engage the bushing between the pin 238 and the arm 251 immediately raising the bars 235 a slight amount aligning the top ends of the bottom inclined portions of the slots 388 with the projecting ends of the pin 387. At the same instant, the roller 252 of the arm 251 will roll onto the shallower cut surface 258 of the bottom cam surface 253 of the cam disc 90 causing the bars 235 to be raised the maximum distance under the influence of the cam plus the additional distance added by the inter-position of the bushing 381 between the free end of the arm 251 and the pin 238. This added movement of the bars 235 will cause the bottom inclined portions of the slots 388 to ride across the ends of the pin 387 drawing outward on the pressure foot 177 against the action of the spring 180 freeing the belt 174 to be fed downward through the hole 175 formed in the platform 65.

The act of separating the clutch discs 82 and 85 closed a normally open auxiliary clutch 389, see Figs. 1, 6 to 8 and 13, to continuously drive the feed roll 260, when the pressure foot 177 is retracted, to feed the end of the completed belt 174 downward to drop through the hole 175 in the platform 65. The auxiliary clutch 389 is comprised of a circular portion of friction material 390, see Fig. 6, fixedly mounted on the bottom end of the tubular shaft 80 which is keyed to the driven shaft 76 so that the tubular shaft 80 rotates with the driven shaft 76 in all of the vertical shifted positions of the tubular shaft 80 on the driven shaft. The bottom end of the sleeve 344 is formed with an internal recess 391 matching the shape of the friction material 390 so that when the tubular shaft 80 is pressed downward for the purpose of disengaging the clutch disc 82 from the clutch disc 85, the recessed bottom end of the sleeve 344 will be pressed into frictional engagement with the friction material 390 causing the sleeve 344 to rotate with the driven shaft 76 and the tubular shaft 80. During normal operation of the machine, the recessed bottom end 391 of the sleeve 344 merely rests on the friction material, but due to the drag on the feed roll 260 created by the fact that the belt 174 is being held by the pressure foot 177, that normal frictional contact is insufficient to rotate the sleeve 344.

Mounted on the sleeve 344, there is a pulley wheel 392. The pulley wheel 392 is fixedly re-

26

tained in position on the sleeve 344 by opposed dish-shaped clamp members 393 which engage the top and bottom faces of the pulley wheel 392. The bottom-most dish-shaped clamp member rests against a circumferential flange 394 formed on the bottom end of the sleeve 344.

The topmost dish-shaped member 393 is engaged against the bottom end of the collar 331, so that when the collar 331 is tightened downward on the sleeve 344 the pulley wheel 392 will be secured in position between the dish-shaped clamp members 393.

Engaged over the pulley wheel 392, there is a continuous belt 395 which away from the pulley wheel extends over a pair of idler pulleys 396. The pulleys 396 are individually rotatively supported on opposite sides of a support block 397 mounted on a bracket 398 which extends from one of the tie rods 94, see Figs. 6 and 13. The end 20 of the bracket 398 is attached to a sleeve 399 secured to the respective tie rod 94 in any known manner.

After leaving the idler pulleys 396, the belt 395 is extended upward through a suitable hole formed in the platform 65 and is engaged over a drive pulley 400, see Figs. 4, 8 and 9, fixedly mounted on the drive shaft 262 on the side of the bracket 264 opposed to the side on which the feed roll 260 is mounted. It is apparent that the separation of the clutch disc 82 and 85 will bring the auxiliary clutch 389 into operation to continuously rotate the feed roll 260, to feed the completed belt 174 free of the machine, during the entire time that the clutch discs 82 and 85 are separated. The gears 271 and 272 will of course rotate with the feed roll 260, but their direction of rotation will be such that the teeth of the gear 272 will merely idle past the pawl 279.

As shown in Figs. 29 and 33, each belt 174 is started by a tongue member 401 formed with a plurality of holes 402 which permit the tongue member 401 to be engaged with a conventional buckle in the usual manner. Adjacent one end, the tongue member 401 is formed with a pair of slots 403 with which the first two links 152 are engaged at the start of the belt. The tongue members 401 are vertically arranged in a magazine 404, see Figs. 1, 2, 5, 20 and 21, suitably supported in position above the machine. The magazine comprises a container having a bottom wall 405, vertical end walls 406 and 407, a front wall 408 and a back wall 409. The top of the container is open so that the tongues may be positioned therein with the slots 403 uppermost, as shown in Fig. 5. The tongues 401 are preformed of preferably the same material which is being used to form the links 152 or of a different material—either of the same or a contrasting color as compared with material being used to form the links 152. As shown in Fig. 5, the bottom wall 405 is positioned with its end spaced slightly from the lower end of the end wall 407 forming an opening 410 through which the tongues 401 are adapted to be discharged one at a time.

The container of the magazine 404 is formed with legs 411 for supporting the magazine in a position above the rods 186 which slidably support the pilot carrier 184, see Fig. 5, and with the opening 410 in position above the inner end of the pressure foot 177 so that the bottom end of a dropped tongue member 401 will fall between the retracted pressure foot 177 and the wall 170 to be engaged between the continuously rotating feed roll 260 and the idler roll 261 to be fed into proper position thereby. The tongue members

401 are arranged one behind the other in the magazine and are pressed against a floating plate 412 by a follower 413 which slides along the bottom wall 405. The top end of the floating plate 412 is curled about a pin 414 as shown in Fig. 5. The pin is wider than the floating plate and extends beyond the sides thereof to slide on the top edges of the front and back walls 408 and 409, as shown in Fig. 2, to freely support the floating plate 412 with its length extended down into the magazine 404 parallel with the tongues 401. Expansion springs 415 operate between the adjacent faces of the end wall 406 and the follower 413 urging the follower into a position in which the tongue members 401 will be pressed against the floating plate 412. The ends of the springs 415 are engaged about studs 416 which extend from the adjacent faces of the end wall 406 and the follower 413.

Means is provided for releasing the floating plate 412 to free the adjacent tongue member 401 to drop from the magazine 404 while at the same time retaining the tongue members 401 back of that adjacent tongue member in position in the magazine. To accomplish this, there is located in the magazine between the adjacent faces of the floating plate 412 and the end wall 407, a pair of parallel superimposed cylindrical keys 417. The keys 417 are formed at their ends with concentrically extended trunnions 418, see especially Figs. 20 and 21, rotatively pressed through complementary holes formed in flanges 419 formed integrally with the end wall 407 and projected beyond the respective front wall 408 or back wall 409. The front and back walls 408 and 409 are formed with appropriately located openings through which the end portions of the cylindrical keys 417 are extended. Mounted on each of the cylindrical keys 417 intermediate of its ends, there is a stud 420. Each stud 420 is freely extended through a vertical elongated slot 421 formed in the end wall 407, see Fig. 5. Each cylindrical key 417 on the side diametrically opposite the side from which the respective stud 420 extends, is formed with a flat surface 422, see Figs. 5 and 20.

The outer ends of the studs 420 are pivotally connected to a vertical tie member 423 by means of pins 424. The bottom end of the tie member 423 is located above the uncurling head 241 and is formed with a laterally extending flange 425. An adjustment screw 426 is threaded through the flange 425 and is secured in a desired adjusted position by a lock nut 427 which is to be tightened against the top face of the flange 425.

A contraction spring 428, see Fig. 1, has one end attached to the end wall 407 and its other end attached to an intermediate portion of the tie member 423 for urging the tie member into its lowered position and retaining the cylindrical keys 417 in a turned position in which the flat surfaces 422 will be turned away from the adjacent face of the floating plate 412 to retain the floating plate pressed against the adjacent tongue member 401, as shown in Figs. 5 and 20.

During normal upward movement of the uncurling head 241 with the bars 235, the adjustment screw 426 is so adjusted that the top face of the uncurling head will not strike the bottom end of the adjustment screw. On the other hand, the adjustment screw 426 is so set, that following the discharge of the completed belt 174 and when the bushing 381 is engaged between the pin 238 and the arm 251 for causing the bars 235 and the uncurling head 241 to be raised the extra amount

to retract the pressure foot 177 against the action of the spring 188, the top face of the uncurling head 241 will strike the bottom end of the adjustment screw 426 and push upward thereon. This will cause the tie member 423 to be raised against the action of the spring 428 and turn the cylindrical keys 417 to a position in which their flat surfaces 422 will be facing the floating member 412 freeing the floating member for slight movement toward the end wall 407, as shown in Fig. 21, which in turn frees the adjacent tongue member 401 to drop downward through the opening 410.

The mechanism for retaining the remaining 15 tongue members 401 in position in the magazine 404 during the time that the adjacent tongue member is being freed to drop through the opening 410 is controlled by the turning movement of the cylindrical keys 417. That mechanism 20 comprises vertical shafts 429 which are extended along the outside faces of the front and back walls 408 and 409 and which have their top and bottom ends rotatively supported in flanges 430 which project laterally from the front and rear walls. Metallic members 431 are arranged one 25 above the other on each of the vertical shafts 429. Each metallic member 431 has an intermediate portion bent about the respective vertical shaft 429 and adjacent radially extending portions 30 through which screws 432 are engaged for clamping the metallic members 431 in position on the shafts 429.

One of the radially extending portions of each 35 of the metallic members 431 continues into a tail portion 433 which bears against the respective cylindrical key 417, see Figs. 20 and 21. The other radially extending portion of each of the metallic members 431 continues into a right angularly 40 extended beveled nose portion 434. The beveled nose portions 434 have their reduced ends 45 aligned with the contacting faces of the two tongue members 401 most closely adjacent the floating plate 412. Coaxially wound on each of the vertical shafts 429 between the metallic members 431, there is a spring 435, see Fig. 1. One end of each spring 435 is connected to the adjacent flange 419 and the other end is connected to the respective vertical shaft 429 and the springs are under a slight tension to turn the shafts into a 50 position in which the tail portions 433 will be retained in engagement with the cylindrical keys 417.

Normally, the metallic members 431 will be in the position shown in Fig. 20 in which their beveled nose portions 434 will be withdrawn from between the adjacent faces of the tongue members 401 so that the follower 413 will be free under the influence of the springs 415, to urge all of the tongue members 401 against the floating plate 412 and the floating plate in turn against the cylindrical keys 417, as shown in Figs. 5 and 20. However, when the cylindrical keys 417 are turned to the position shown in Fig. 21 to align the flat surfaces 422 of the keys 417 with the floating plate 412, such action will also align the flat surfaces with the tail portions 433 of the metallic members. This will free the metallic members 431 so that the shafts 429 can be turned by the springs 435 to engage the nose portions 55 434 of the metallic members 431 between the adjacent faces of the tongue member 401 which is in face engagement with the floating plate 412 and the tongue member next removed from the floating plate, as shown in Fig. 21. The nose portions 60 434 will hold the remaining tongue mem-

bers from being pressed forward by the follower 413 and leave the tongue member 401 immediately adjacent the floating plate 412 free to drop through the opening 410 and into the machine.

Means is provided for pivoting the lever 320, against the holding action of the detent 319 and the leaf spring 322, to unseat the pointed portion 327 of the link 325 from the shoulder 323 freeing the link 325 to pivot back to its starting position. That means is controlled by the dropping of the tongue member 401 from the magazine 404 and frees the machine for normal operation to form another belt 174, and includes a rod 436, see Figs. 4, 7 and 17. The rod 436 has one end slidably supported in the bracket 324 above the link 325 so that that end can be forced against the top free end of the lever 320 to pivot it. The opposite end of the rod 436 is slidably extended through an upstanding portion 437^a of a bracket 437. The bracket 437 is secured in position on the platform 65 by several bolts 438 which pass through a foot portion 437^b of the bracket and threadedly engage the platform, see Fig. 4.

A sleeve 439 is positioned on the rod 436 between the bracket 324 and the bracket 437 and is secured in a desired adjusted position by a set screw 440. An expansion spring 441 is coaxially wound on the rod 436 and operates between the upstanding portion 437^a of the bracket 437 and the adjacent end of the sleeve 439 for urging of the rod 435 toward the lever 320. Adjustment of the sleeve 439 on the rod 436 will vary the tension of the spring 441.

Mechanism is provided for drawing the rod 436 in a direction away from the lever 320, against the action of the spring 441, and for holding the rod 436 and the spring in that loaded position. That means comprises a vertical shaft 442 which is rotatively supported in a pair of superimposed lug portions 437^c and 437^d which project from the bracket 437. Extended from the top end of the vertical shaft 442, there is a long lever 443 which has a free end overlying the top face of the cam disc 90. The other end is formed with a vertical groove, see Fig. 4, in which one side of the top end of the vertical shaft 442 is nested. A small plate 445 is positioned along the other side of the top end of the vertical shaft 442 and is formed with a vertical groove which cooperates with the vertical groove of the long lever 443 to form a passage for the top end of the vertical shaft. Positioned against the side of the long lever 443 on the side opposite that engaged by the top end of the vertical shaft 442, there is a metallic member 446. The long lever 443, the small plate 445 and the metallic member 446 are secured together by nut and bolt assemblies 447 passed through those parts and which also fixedly mount those parts on the top end of the vertical shaft 442, see Fig. 2.

Fixedly mounted on the end of the rod 436, opposed to the end which is to engage the lever 320, there is a collar 448. The metallic member 446 has an end portion which is bent to extend away from the adjacent face of the long lever 443 and which is formed with a slot 449, see especially Fig. 7, through which the portion of the rod 436, between the collar 448 and the bracket 437, passes. Thus, when the free end of the long lever 443 is moved outward with relation to the top face of the cam disc 90, the shaft 442 will be turned and the metallic member 446 will be moved in a direction to cause the rod 436 to be moved away from the lever 320 against the action of the spring 441.

Intermediate of its ends, the vertical shaft 442 carries a collar 450 which rests on the top face of the lug portion 437^c for turnably supporting the vertical shaft 442 at the proper elevation with relation to the lug portions 437^c and 437^d. The bottom end of the vertical shaft 442 is projected below the bottom face of the bottom lug portion 437^d and has fixedly mounted thereon a cam 451. The bracket 437 is formed with a horizontal portion 437^e which is extended in the direction opposite to the direction in which the lug portions 437^c and 437^d are extended. Pivoted to the free end of the horizontal portion 437^e, by means of a pivot pin 452, there is an L-shaped member 453, best shown in Figs. 4, 17 and 18. The pivotally mounted arm of the L-shaped member 453 bears against the side of the cam 451. A contraction spring 454, see Fig. 4, has one end attached to the free end of the free arm of the L-shaped member 453 and its other end attached to a lug 455 attached to a fixed part of the machine. The contraction spring 454 exerts a force which draws the L-shaped member 453 into a position in which its pivotally mounted arm bears against the side of the cam 451, see Fig. 18, to turn the vertical shaft 442 into a position in which the free end of the long lever 443 fully overlies the top face of the cam disc 90.

A control lever 456 has one end positioned between the adjacent faces of the lug portions 437^c and 437^d, as clearly shown in Fig. 17. That end of the control lever 456 is pivotally supported on the bracket 437 by means of a pivot pin 457 so that the control lever 456 can be pivoted in a vertical plane. The short end of the control lever 456 is formed with a depending tab portion 458 which is designed to engage a complementary niche 459 formed in the top face of the cam 451 when the cam has been turned against the action of the spring 454, by the vertical shaft 442, to a position in which the free end of the long lever 443 is moved outward with relation to the top face of the cam disc 90. In this position, the rod 436 will be retracted against the action of the spring 441, as shown in Fig. 7. A spring 460 has one end connected to a pin 461 that projects from the control lever 456 and its other end connected to a lug 462 which extends from the bracket 437. The spring 460 functions to turn the control lever into a position in which the depending tab portion 458 will retain engagement with the niche 459 of the cam 451. The adjacent arm of the L-shaped member 453 is formed with a niche 463 so as not to interfere with the operation of the cam and the engagement and disengagement of the tab portion 458 with the niche 459 of the cam.

Mechanism is provided, controlled by the dropping of the new tongue member 401 from the magazine 404, for pivoting the control lever 456, at the precise moment when the lowermost slot 403 of the tongue member 401 becomes aligned with the pilot 182 and the feeder 183, to free the cam 451 so that the shaft 442 can turn and release the rod 436. The rod 436 will then be urged by the spring 441 in a direction to strike the top end of the lever 320 unseating the pointed portion 327 of the link 325 from the shoulder 323 freeing the machine to return to normal operation and successively add links 152 to the new tongue member 401 to form the next belt. The flexible nature of the leaf spring 322 permits the rod 436 to pivot the lever 320 notwithstanding the fact that the detent 319 is still in a posi-

tion holding the lever 320 in its vertical pivoted position on the bar 309.

That mechanism is comprised of a block 464, see Figs. 4, 9 and 12, mounted on an extended end of the shaft 266 upon which the idler roll 261 is mounted. Slidably extended through a vertical hole 465 formed in the block 464, there is a vertical rod 466. The top end of the vertical rod 466 is projected through an opening 467 formed in the top wall 61 of the casing, see Figs. 3 and 12, and has a top end portion 468 bent at right angles thereto and extended partially across the face of the uncurling head 241. The free end of the top end portion is depended downward and is formed with a hook portion 469, see Figs. 5, 9 and 12, extended toward the adjacent face of the uncurling head 241. The vertical rod 466 is urged into a raised position with relation to its supporting block 464 by means of a contraction spring 470 having one end connected to a pin 471 which extends from the block 464 and its other end connected to a pin 472 mounted on the bottom end of the rod 466 which extends from the bottom of the block 464.

The pin 472 is comparatively long and has its free end passed through a vertical slot 473, see Figs. 9 and 12, formed in a flat bar 474. The top end of the bar 474 is supported for pivotal movement, by means of a pin 474, upon a bracket 476 which is secured to the side of the bracket 169 by several screws 477. The bottom end of the bar 474 engages a guide member 478 secured to the platform 65, and is formed with a laterally extending portion 479 having a depending finger 480. The finger 480 is spaced slightly from the adjacent side of the bottom end of the bar 474 to engage a shoulder 481 formed on the guide member 478 for limiting turning movement of the bar 474 in a counter-clockwise direction as viewed in Fig. 9.

A link 482 has one end pivotally connected to the laterally extending portion 479 of the bar 474 by means of a pin 483. The other end of the link 482 is connected to the bottom end of another link 484 by means of a pin 485. The top end of the link 484 is fixedly connected to one end of a shaft 486. The shaft is rotatively supported, at its end adjacent the link 484, in the top end of a bracket 487 which extends vertically from the platform 65. The other end of the shaft 486 is rotatively supported in a right angular extension 437^{dd} of the lug portion 437^d of the bracket 437. A flexible member 488 has one end fixedly secured to the end of the shaft 486 and its other end extended upward therefrom and bears against the end of the rod 436 beyond the collar 448, see Figs 4 and 7. The bottom end of the flexible member 488 is inserted into a slot 489 cut in the end of the shaft 486 and secured in position therein by a rivet 490. A coil spring 491 is coaxially wound on the shaft 486, see Fig. 4, and has one end attached to the bracket 487 and the other end attached to the top end of the link 484 for turning the shaft 486 in a direction to move the finger 480 away from the shoulder 481 and for retaining the top end of the flexible member 488 in contact with the adjacent end of the rod 436.

The long control lever 456 has its longer free end extended to the rear of the machine, see Figs. 4 and 12, and has mounted on the free end thereof a foot member 492, see especially Fig. 12. The foot member 492 has a vertical portion extended along the free end of the control lever 456 and is formed with a vertical slot 493 through which a screw 494 passes for vertically adjusting

the position of the foot member 492 on the end of the control lever. The foot member 492 further has a horizontal portion which is to be struck by the bottom end of the vertical rod 466 when it is moved downward against the action of its spring 470 for pivoting the control lever 456 against the action of its spring 468 to disengage the tab portion 458 from the cam 451 freeing the cam and the vertical shaft 442 to be turned. A stop screw 495 is threaded vertically through the platform 65 beneath the horizontal portion of the foot member 492 and is secured in a desired vertically adjusted position by a lock nut 496 for limiting pivoting of the control lever 456 when the horizontal portion of the foot member 492 strikes the top end of the stop screw 495.

When the tongue member 401 is released by the magazine 404 it will drop downward with its slot 403 at the upper end thereof, which is the position shown in Fig. 5. At this time the pressure foot 177 will be in its retracted position due to the fact that the bars 235 and the uncurling head 241 have been raised the extra amount required to release the tongue member 401 from the magazine 404, as previously described. The previously completed belt 174 has been discharged from the machine and the idler roll 261 has been urged by its springs 270, into a position in which it contacts the now continuously driven feed roll 260. In this position, the block 464 which supports the vertical rod 466 will have been moved slightly to the right as viewed in Fig. 9 causing the rod 466 to be turned slightly due to the engagement of the pin 472 with the slot 473 in the bar 474—the bar 474 being retained from pivoting to the right, as viewed in Fig. 9, by the engagement of the depending finger 480 with the shoulder 481. The slight turning of the vertical rod 466 will space the hook portion 469 just sufficiently from the adjacent face of the uncurling head 241 so that the bottom end of the released tongue member 401 can pass between the uncurling head and the hook portion 469 to drop into the machine until its bottom end rests against the top of the contacting surfaces of the rolls 260 and 261. In this position, the lower of the two slots 403 of the dropped tongue member 401 will still be slightly above the hook portion 469.

As the feed roll 260 is being continuously rotated, due to the engagement of the auxiliary clutch 389, it will cooperate with the idler roll 261 to feed the tongue member 401 downward. As the bottom end of the tongue member 401 engages between the contact surfaces of the rolls 260 and 261, the idler roll 261 will be spaced slightly from the feed roll 260 due to the thickness of the material from which the tongue member 401 is made. That movement of the idler roll 261 will cause the block 464 supporting the vertical rod 466 to be moved to the left, as viewed in Fig. 9, causing the free end of the hook portion 469 to bear frictionally against the tongue member 401. As the bottommost slot 403 of the tongue member 401 approaches the hook portion 469, the pressure on the rod 466 will cause the hook portion 469 to be snapped into that bottommost slot 403. As further downward movement of the tongue member 401 is effected by the rolls 260 and 261, the rod 466 will be carried downward by the tongue member against the action of its spring 470. As that bottommost slot 403 approaches a horizontal point aligned with the pilot 182 and the feeder 183, the bottom end of the vertical rod 466 will strike the horizontal portion of the foot member 492 to pivot the con-

trol lever 456 against the action of its spring 460. When the bottommost slot 403 reaches that horizontal position aligned with the pilot 182 and the feeder 183, the rod 436 will be in its completely lowered position in which the horizontal portion of the foot member 492 will be resting on the top end of the stop screw 495. In that position, the tab portion 458 will be completely disengaged from the niche 459 in the cam 451. The tension on the spring 454 will turn the cam 451 and in turn the vertical shaft 442 to a position in which the free end of the long lever 443 will be moved inward with relation to the periphery of the cam disc 90. This will in turn move the metallic member 446 to a position in which the rod 436 is free to be urged by its spring 441 in a direction to pivot the lever 320 against the holding action of the leaf spring 322 and the detent 319.

That action releases the link 325 and frees the bar 328 to be urged upward by the spring 341. Immediately the coil spring 91 urges the tubular shaft 80 upward closing the clutch discs 82 and 85 to resume rotation of the cam disc 90 and to release the tension on the auxiliary clutch 389 to stop rotation of the feed roll 260 and retain the dropped tongue member 401 in a position in which the bottommost slot 403 will be in horizontal alignment with the pilot 182 and the feeder 183.

When the link 325 is pivoted, the pin 360 is moved away from the free end of the detent 359, freeing the shaft 358 so that the triangular segmental member 364 could drop by the influence of gravity, back to its starting position withdrawing the pins 367 and 370 from the pawls 306 and 307 so that those pawls could drop under the influence of gravity back to their operative position with relation to the ratchet teeth 297 of the circular disc 296. Simultaneously, tension on the spring 377 is relaxed and the spring 385 will function to pivot the lever 318 in a direction to disengage the bushing 381 from between the pin 238 and the arm 251 restoring that bushing 381 to its starting position. The bars 235 and the uncurling head 241 will then drop downward and the parts of the magazine 404 will be released to return to their starting position. Likewise, the turning of the link 325 will turn the radial arm 325 in a direction to release the tension on the spring 357 freeing the brake control member 347 to be urged by the spring 356 in a direction to relieve the tension on the brake band 345 freeing the cam disc 90 to be rotated by the reengagement of the clutch discs 82 and 85.

At the moment that the rod 436 is urged toward the lever 320, the tension on the flexible member 488 is released freeing the shaft 486 to be turned by the coil spring 491 to cause the flexible member 488 to follow the movement of the rod 436 and to pull on the links 482 and 484 and pivot the bar 474 in a direction to move the depending finger 480 away from the shoulder 481. This movement of the bar 474 will turn the vertical rod 466 in its supporting block 464, due to the engagement of the pin 472 in the slot 473, and disengage the hook portion 469 from the bottommost slot 403 of the tongue member 401. That frees the vertical rod 466 to be raised to its starting position by the tension on the spring 470, and which in turn frees the control lever 456 to be turned by the spring 460 to a position in which the free end of the tab portion 458 rests on the top face of the cam 451.

As rotation of the cam disc 90 is resumed, it will of course operate the punch 99 and will 75 drive the cam disc 90.

cause the first of the links 152 formed by the punch 99 to be moved by the pilot 182 and the feeder 183 toward and into engagement with the bottommost slot 403 of the tongue member 401 and to repeat the process for each additional link 152. However, on the first rotation of that cam disc 90, the crank pin 197 and more particularly the parts carried thereby will engage and pivot the long lever 443 and pivot the vertical shaft 442 causing the metallic member 446 to draw the rod 436 back to its starting position against the action of the spring 441. Simultaneously, the turning of the shaft 442 will cause the cam 451 to be turned to align the niche 459 thereof with the tab portion 458 of the control lever 456 so that the spring 460 may further turn the control lever and engage the tab portion 458 into the niche 459 to lock the rod 436 in its starting position.

Return movement of the rod 436 will tension the flexible member 488 to turn the shaft 486 against the action of the spring 491 to move the links 482 and 484 in a direction to pivot the bar 474 back to its position in which the depending finger 480 contacts the shoulder 481. This will turn the vertical rod 466 back to its starting position with relation to its supporting block 464. If the return movement of the rod 436 is greater than that actually required to restore the bar 474 to its starting position, the additional movement of that rod will be absorbed by the flexible member 488. All of the parts are now back to their starting position, following the discharge of one completed belt, and the machine is conditioned to form a new belt on the new tongue member 401 by successively adding links 152 thereto.

The operation of the machine is as follows:

For the purpose of this brief general description of the operation of the machine, which is all that is believed necessary as the operation of the individual phases of the machine have been set forth in detail in connection with the description of the parts thereof, it is presumed that the supply of tongue members 401 in the magazine 404 is adequate and that a goodly supply of the strip material 101 from which the links 152 are to be formed is in position on the pin 102, see Fig. 1. The machine is stopped with the pins 367 and 370 holding the pawls 306 and 307 out of engagement with the ratchet teeth 297 of the circular disc 296. In this position the control knob 295 can be manipulated, as previously described, to adjust the control detent 298 to form a new belt of a desired length.

Following adjustment of the control knob 295, power for driving the belt 74 and the pulley 75 is restored and the machine is permitted to operate in a normal manner. The uncurling head 241 raised its excessive amount will operate the magazine 404 to release one of the tongue members 401 to drop into its operative position to be fed downward by the rolls 260 and 261 until the bottommost slot 403 of the new tongue member 401 reaches its aligned position with the pilot 182 and the feeder 183, having pulled the vertical rod 466 down with it. When that bottommost slot 403 reaches that aligned position, the vertical rod 466 will function to pivot the control lever 456 to release the cam 451, as previously described. Pivoting of the cam 451 will function to open the auxiliary clutch 389 to stop rotation of the feed roll 260 and to reengage the clutch discs 82 and 85 to re-connect the shafts 76 and 86 and drive the cam disc 90.

Rotation of the cam disc 90 will operate the punch 99 to cut the links 152 from the strip of material 100 and to oscillate the pilot 182 and the feeder 183 to and fro between the punch 99 and the belt 174, being formed, to successively inter-link each new link 152 with the links previously added to the belt 174. The cam disc 90 will also function, following the addition of each additional link 152 to move the belt 174 downward the required amount, by turning the feed roll 260, to align the next group of aligned slots of the belt 174, being formed, with the pilot 182 and the feeder 183 for the addition of the next link. The downward movement of the belt 174 will also serve, as previously described, to move the circular disc 296 one ratchet tooth 297 for each link added to the belt 174.

The operation of the machine continues in this fashion until the final link 152 has been added to the belt and the circular disc 296 has been advanced so that its pin 302 strikes the lug 303. The machine will then function automatically, as previously described, to withdraw the pressure foot 171 to release the completed belt 174, to open the clutch discs 82 and 85 and to close the auxiliary clutch 389 to again rotate the feed roll 260 and feed the completed belt 174 downward to drop through the hole 175 formed in the platform 65. At the same time, the magazine 404 will again be operated to release a new tongue member 401 so that the cycle can repeat itself and form another belt.

The completed belts 174 which drop from the machine can then be finished by having a buckle of any known design attached to the end thereof remote from the tongue member 401, as is well known by those skilled in the art to which the present invention pertains.

From the foregoing description it will be apparent that a belt making machine is provided which is fully automatic in its operation and which requires no attention on the part of an operator beyond replenishing the supply of pre-formed tongues 401 in the magazine 404, replenishing the supply of strip material 100 from which the links 152 are to be formed and adjusting the control knob 295 to adjust the machine to form belts of the desired length.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the align slots for the entrance of said feeder and the carried belt link, and means for oscillating said feeder and said pilot to and fro

between said source of belt links and said belt supporting means and in timed synchronism so that said pilot always enters the aligned slots of the belt being formed in advance of said feeder and the belt link carried thereby.

2. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot.

3. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot,

4. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the align slots for the entrance of said feeder and the carried belt link, and means for oscillating said feeder and said pilot to and fro

belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, said source of belt links comprising a punch for successively cutting the belt links from a continuous strip of material, the belt links being shaped to have a rounded head portion, a reduced neck portion and a body portion with one slot in said head portion and two slots in said body portion, said punch being arranged to form the free end of the body portion of one link severing that link from said continuous strip of material and to form the rounded head portion, the reduced neck portion and the slots of the next link for each operation of the punch.

5. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, said source of belt links comprising a punch for successively cutting the belt links from a continuous strip of material, the belt links being shaped to have a rounded head portion, a reduced neck portion and a body portion with one slot in said head portion and two slots in said body portion, said punch being arranged to form the free end of the body portion of one link severing that link from said continuous strip of material and to form the rounded head portion, the reduced neck portion and the slots of the next link for each operation of the punch, said punch being operated in timed synchronization with the to and fro movement of said feeder and said pilot by said cam disc.

6. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a

horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, said source of belt links comprising a punch for successively cutting the belt links from a continuous strip of material, the belt links being shaped to have a rounded head portion, a reduced neck portion and a body portion with one slot in said head portion and two slots in said body portion, said punch being arranged to form the free end of the body portion of one link severing that link from said continuous strip of material and to form the rounded head portion, the reduced neck portion and the slots of the next link for each operation of the punch, and transfer mechanism carried by said pilot for moving the severed belt link from said punch into position on said feeder prior to the time that said feeder starts its movement from said punch to said belt supporting means.

7. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, said source of belt links comprising a punch for successively cutting the belt links from a continuous strip of material, the belt links being shaped to have a rounded head portion, a reduced neck portion and a body portion with one slot in said head portion and two slots in said body portion, said punch being arranged to form the free end of the body portion of one link severing that link from said continuous strip of material and to form the rounded head portion, the reduced neck portion and the slots of the next link for each operation of the punch, and transfer mechanism carried by said pilot for moving the severed belt link from said punch into position on said feeder prior to the time that said feeder starts its movement from said punch to said belt supporting means.

operation of the punch, and means loaded by said pilot as it moves from said belt supporting means to said punch to advance said continuous strip of material to move the partially formed belt link into position to have the free end of the body portion formed on the next operation of said punch when said pilot moves from said punch to said belt supporting means.

8. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, each belt link having a rounded head portion wider than the length of the aligned slots of the belt and a reduced neck portion of a width slightly less than the length of the aligned slots of the belt, the belt links being carried by said feeder toward the aligned slots of the belt with their rounded head portions first, curling arms pivotally mounted on said casing to be moved together to engage and curl inward the sides of the rounded head portion of the belt link carried by said feeder to reduce the width thereof so that the rounded head portion can be passed through the aligned slots, and means on said pilot for moving said curling arms into operative position just prior to the time that said feeder approaches the aligned slots of the belt.

9. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, each belt link having a rounded head portion wider than the length of the aligned slots of the belt and a reduced neck portion of a width slightly less than the length of the aligned slots of the belt, the belt links being carried by said feeder toward the aligned slots of the belt with their rounded head portions first, curling arms pivotally mounted on said casing to be moved together to engage and curl inward the sides of the rounded head portion of the belt link carried by said feeder to reduce the width thereof so that the rounded head portion can be passed through the aligned slots, and means on said pilot for moving said curling arms into operative position just prior to the time that said feeder approaches the aligned slots of the belt.

centrically pivotally connected to said cam disc and their other ends pivotally connected respectively to said feeder or said pilot, each belt link having a rounded head portion wider than the length of the aligned slots of the belt and a reduced neck portion of a width slightly less than the length of the aligned slots of the belt, the belt links being carried by said feeder toward the aligned slots of the belt with their rounded head portions first, curling arms pivotally mounted on said casing to be moved together to engage and curl inward the sides of the rounded head portion of the belt link carried by said feeder to reduce the width thereof so that the rounded head portion can be passed through the aligned slots, and means on said pilot for moving said curling arms into operative position just prior to the time that said feeder approaches the aligned slots of the belt, and an uncurling head positioned on the side of the belt opposite that approached by said feeder for uncurling the rounded head portion of the belt after it has been passed through said aligned slots of the belt.

10. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, each belt link having a rounded head portion wider than the length of the aligned slots of the belt and a reduced neck portion of a width slightly less than the length of the aligned slots of the belt, the belt links being carried by said feeder toward the aligned slots of the belt with their rounded head portions first, curling arms pivotally mounted on said casing to be moved together to engage and curl inward the sides of the rounded head portion of the belt link carried by said feeder to reduce the width thereof so that the rounded head portion can be passed through the aligned slots, and means on said pilot for moving said curling arms into operative position just prior to the time that said feeder approaches the aligned slots of the belt, and an uncurling head positioned on the side of the belt opposite that approached by said feeder for uncurling the rounded head portion of the belt after it has been passed through said aligned slots of the belt, bars vertically slidably supported by said casing and upon which said uncurling head is fixedly mounted, a block fixedly mounted beneath said uncurling head at a level to have said feeder slide across the top face thereof after passing through the aligned slots of the

belt, and means controlled by said cam disc for lowering said bars to in turn lower said uncurling head to bear frictionally against the top of the link passed through the aligned slots of the belt for retaining that link in position while said feeder is being withdrawn from the aligned slots of the belt.

11. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, each belt link having a rounded head portion wider than the length of the aligned slots of the belt and a reduced neck portion of a width slightly less than the length of the aligned slots of the belt, the belt links being carried by said feeder toward the aligned slots of the belt with their rounded head portions first, curling arms pivotally mounted on said casing to be moved together to engage and curl inward the sides of the rounded head portion of the belt link carried by said feeder to reduce the width thereof so that the rounded head portion can be passed through the aligned slots, and means on said pilot for moving said curling arms into operative position just prior to the time that said feeder approaches the aligned slots of the belt, and an uncurling head positioned on the side of the belt opposite that approached by said feeder for uncurling the rounded head portion of the belt after it has been passed through said aligned slots of the belt, bars vertically slidably supported by said casing and upon which said uncurling head is fixedly mounted, a block fixedly mounted beneath said uncurling head at a level to have said feeder slide across the top face thereof after passing through the aligned slots of the belt, and means controlled by said cam disc for lowering said bars to in turn lower said uncurling head to bear frictionally against the top of the link passed through the aligned slots of the belt for retaining that link in position while said feeder is being withdrawn from the aligned slots of the belt, said block being supported on a bracket within said casing, a pressure foot slidably mounted on said block for movement toward and away from said bracket, the belt being passed downward between said bracket and said pressure foot, and resilient means urging said pressure foot toward said bracket to support the belt with the aligned slots in a proper position.

12. A belt making machine comprising a cas-

ing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, each belt link having a rounded head portion wider than the length of the aligned slots of the belt and a reduced neck portion of a width slightly less than the length of the aligned slots of the belt, the belt links being carried by said feeder toward the aligned slots of the belt with their rounded head portions first, curling arms pivotally mounted on said casing to be moved together to engage and curl inward the sides of the rounded head portion of the belt link carried by said feeder to reduce the width thereof so that the rounded head portion can be passed through the aligned slots, and means on said pilot for moving said curling arms into operative position just prior to the time that said feeder approaches the aligned slots of the belt, and an uncurling head positioned on the side of the belt opposite that approached by said feeder for uncurling the rounded head portion of the belt after it has been passed through said aligned slots of the belt, bars vertically slidably supported by said casing and upon which said uncurling head is fixedly mounted, a block fixedly mounted beneath said uncurling head at a level to have said feeder slide across the top face thereof after passing through the aligned slots of the belt, and means controlled by said cam disc for lowering said bars to in turn lower said uncurling head to bear frictionally against the top of the link passed through the aligned slots of the belt for retaining that link in position while said feeder is being withdrawn from the aligned slots of the belt, said block being supported on a bracket within said casing, a pressure foot slidably mounted on said block for movement toward and away from said bracket, the belt being passed downward between said bracket and said pressure foot, and resilient means urging said pressure foot toward said bracket to support the belt with the aligned slots in a proper position, rolls supported beneath said pressure foot and between which the belt passes, and means operated by said cam disc for periodically turning said rolls to move the belt downward following the addition of each link for aligning another group of aligned slots with said feeder and said pilot.

13. A belt making machine comprising a casing, a source of belt links at one end of said casing, a feeder slidably mounted on said casing for

successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, and means operated by said cam disc for moving the belt downward following the addition of each belt link for aligning another group of aligned slots with said feeder and said pilot.

14. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots in a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, and means operated by said cam disc for moving the belt downward following the addition of each belt link for aligning another group of aligned slots with said feeder and said pilot, manually adjustable mechanism including a rotative circular disc having ratchet teeth about its periphery for controlling the number of links which will be interlinked to form each belt, and a gravity actuated pawl for advancing said circular disc one tooth each time another link is added to the belt, said pawl being operated by said means for moving the belt downward to advance said circular disc.

15. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots

on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, and means operated by said cam disc for moving the belt downward following the addition of each belt link for aligning another group of aligned slots with said feeder and said pilot, manually adjustable mechanism including a rotative circular disc having ratchet teeth about its periphery for controlling the number of links which will be interlinked to form each belt, and a gravity actuated pawl for advancing said circular disc one tooth each time another link is added to the belt, said pawl being operated by said means for moving the belt downward to advance said circular disc, said manually adjustable mechanism including an adjustable control detent presettable for any desired number of links, a stop pin mounted on said circular disc, and resilient means urging said circular disc against the action of said pawl into a position in which said stop pin engages said control detent.

16. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, and means operated by said cam disc for moving the belt downward following the addition of each belt link for aligning another group of aligned slots with said feeder and said pilot, manually adjustable mechanism including a rotative circular disc having ratchet teeth about its periphery for controlling the number of links which will be interlinked to form each belt.

belt, and a gravity actuated pawl for advancing said circular disc one tooth each time another link is added to the belt, said pawl being operated by said means for moving the belt downward to advance said circular disc, said manually adjustable mechanism including an adjustable control detent presetable for any desired number of links, a stop pin mounted on said circular disc, and resilient means urging said circular disc against the action of said pawl into a position in which said stop pin engages said control detent, and means operated by said stop pin when the last link is added to the belt to stop power rotation of said cam disc and to continuously operate said means for moving the belt downward to feed the completed belt out of the bottom of the machine.

17. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, and means operated by said cam disc for moving the belt downward following the addition of each belt link for aligning another group of aligned slots with said feeder and said pilot, manually adjustable mechanism including a rotative circular disc having ratchet teeth about its periphery for controlling the number of links which will be interlinked to form each belt, and a gravity actuated pawl for advancing said circular disc one tooth each time another link is added to the belt, said pawl being operated by said means for moving the belt downward to advance said circular disc, said manually adjustable mechanism including an adjustable control detent presetable for any desired number of links, a stop pin mounted on said circular disc, and resilient means urging said circular disc against the action of said pawl into a position in which said stop pin engages said control detent, and means operated by said stop pin when the last link is added to the belt to stop power rotation of said cam disc and to continuously operate said means for moving the belt downward to feed the completed belt out of the bottom of the machine, said means operated by said stop comprising a drive including a normally closed clutch for driving said cam disc, and a normally opened auxiliary clutch for continuously operating said means for moving the belt downward, said clutches being operated in unison and in opposition to one another.

18. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, and means operated by said cam disc for moving the belt downward following the addition of each belt link for aligning another group of aligned slots with said feeder and said pilot, manually adjustable mechanism including a rotative circular disc having ratchet teeth about its periphery for controlling the number of links which will be interlinked to form each belt, and a gravity actuated pawl for advancing said circular disc one tooth each time another link is added to the belt, said pawl being operated by said means for moving the belt downward to advance said circular disc, said manually adjustable mechanism including an adjustable control detent presetable for any desired number of links, a stop pin mounted on said circular disc, and resilient means urging said circular disc against the action of said pawl into a position in which said stop pin engages said control detent, and means operated by said stop pin when the last link is added to the belt to stop power rotation of said cam disc and to continuously operate said means for moving the belt downward to feed the completed belt out of the bottom of the machine, said means operated by said stop comprising a drive including a normally closed clutch for driving said cam disc, and a normally opened auxiliary clutch for continuously operating said means for moving the belt downward, said clutches being operated in unison and in opposition to one another.

19. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said

source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, and means operated by said cam disc for moving the belt downward following the addition of each belt link for aligning another group of aligned slots with said feeder and said pilot, manually adjustable mechanism including a rotative circular disc having ratchet teeth about its periphery for controlling the number of links which will be interlinked to form each belt, and a gravity actuated pawl for advancing said circular disc one tooth each time another link is added to the belt, said pawl being operated by said means for moving the belt downward to advance said circular disc, said manually adjustable mechanism including an adjustable control detent presettable for any desired number of links, a stop pin mounted on said circular disc, and resilient means urging said circular disc against the action of said pawl into a position in which said stop pin engages said control detent, and means operated by said stop pin when the last link is added to the belt to stop power rotation of said cam disc and to continuously operate said means for moving the belt downward to feed the completed belt out of the bottom of the machine, said means operated by said stop comprising a drive including a normally closed clutch for driving said cam disc, and a normally opened auxiliary clutch for continuously operating said means for moving the belt downward, said clutches being operated in unison and in opposition to one another, a continuously driven shaft, said normally closed clutch including a fixed clutch disc connected to said cam disc and a clutch disc slidable on said driven shaft, means operated by said stop pin for causing movement of said slidable clutch disc toward and away from said fixed clutch disc, said auxiliary clutch being mounted on said driven shaft, and means interconnecting said slidable clutch disc and said auxiliary clutch to cause said auxiliary clutch to be engaged when said movable clutch disc is moved away from said fixed clutch disc.

20. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc

and their other ends pivotally connected respectively to said feeder or said pilot, and means operated by said cam disc for moving the belt downward following the addition of each belt link for aligning another group of aligned slots with said feeder and said pilot, manually adjustable mechanism including a rotative circular disc having ratchet teeth about its periphery for controlling the number of links which will be interlinked to form each belt, and a gravity actuated pawl for advancing said circular disc one tooth each time another link is added to the belt, said pawl being operated by said means for moving the belt downward to advance said circular disc, said manually adjustable mechanism including an adjustable control detent presettable for any desired number of links, a stop pin mounted on said circular disc, and resilient means urging said circular disc against the action of said pawl into a position in which said stop pin engages said control detent, and means operated by said stop pin when the last link is added to the belt to stop power rotation of said cam disc and to continuously operate said means for moving the belt downward to feed the completed belt out of the bottom of the machine, the belt including a pre-formed tongue member having slots with which the first belt links are interengaged, a magazine supported above the machine for a plurality of the tongue members, said magazine being formed with an opening above said belt supporting means through which said tongue members are to drop to be properly supported by said belt supporting means following the discharge of a completed belt from the machine, and mechanism for releasing a single tongue member to drop through said opening, said releasing mechanism being operated by said stop pin in synchronization with said means for continuously operating said means for moving the belt downward.

21. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, and means operated by said cam disc for moving the belt downward following the addition of each belt link for aligning another group of aligned slots with said feeder and said pilot, manually adjustable mechanism including a rotative circular disc having ratchet teeth about its periphery for controlling the number of links which will be interlinked to form each belt, and a gravity actuated

pawl for advancing said circular disc one tooth each time another link is added to the belt, said pawl being operated by said means for moving the belt downward to advance said circular disc, said manually adjustable mechanism including an adjustable control detent presetable for any desired number of links, a stop pin mounted on said circular disc, and resilient means urging said circular disc against the action of said pawl into a position in which said stop pin engages said control detent, and means operated by said stop pin when the last link is added to the belt to stop power rotation of said cam disc and to continuously operate said means for moving the belt downward to feed the completed belt out of the bottom of the machine, the belt including a pre-formed tongue member having slots with which the first belt links are interengaged, a magazine supported above the machine for a plurality of the tongue members, said magazine being formed with an opening above said belt supporting means through which said tongue members are to drop to be properly supported by said belt supporting means following the discharge of a completed belt from the machine, and mechanism for releasing a single tongue member to drop through said opening, said releasing mechanism being operated by said stop pin in synchronization with said means for continuously operating said means for moving the belt downward, and mechanism controlled by the dropping of the tongue member from said magazine for rendering the means operated by said stop pin inoperative so that said cam disc can again be rotated.

22. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, and means operated by said cam disc for moving the belt downward following the addition of each belt link for aligning another group of aligned slots with said feeder and said pilot, manually adjustable mechanism including a rotative circular disc having ratchet teeth about its periphery for controlling the number of links which will be inter-linked to form each belt, and a gravity actuated pawl for advancing said circular disc one tooth each time another link is added to the belt, said pawl being operated by said means for moving the belt downward to advance said circular disc, said manually adjustable mechanism including an adjustable control detent presetable for any

desired number of links, a stop pin mounted on said circular disc, and resilient means urging said circular disc against the action of said pawl into a position in which said stop pin engages said control detent, and means operated by said stop pin when the last link is added to the belt to stop power rotation of said cam disc and to continuously operate said means for moving the belt downward to feed the completed belt out of the bottom of the machine, a normally inoperative brake surrounding said cam disc, and means operated by said stop pin for rendering said brake operative to hold said cam disc from further rotation by the act of inertia when power rotation of the cam disc is stopped.

23. A belt making machine comprising a casing, a source of belt links at one end of said casing, a feeder slidably mounted on said casing for successively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotedly connected to said cam disc and their other ends pivotedly connected respectively to said feeder or said pilot, and means operated by said cam disc for moving the belt downward following the addition of each belt link for aligning another group of aligned slots with said feeder and said pilot, manually adjustable mechanism including a rotative circular disc having ratchet teeth about its periphery for controlling the number of links which will be interlinked to form each belt, and a gravity actuated pawl for advancing said circular disc one tooth each time another link is added to the belt, said pawl being operated by said means for moving the belt downward to advance said circular disc, said manually adjustable mechanism including an adjustable control detent presetable for any desired number of links, a stop pin mounted on said circular disc, and resilient means urging said circular disc against the action of said pawl into a position in which said stop pin engages said control detent, and means operated by said stop pin when the last link is added to the belt to stop power rotation of said cam disc and to continuously operate said means for moving the belt downward to feed the completed belt out of the bottom of the machine, a normally inoperative brake surrounding said cam disc, and means operated by said stop pin for rendering said brake operative to hold said cam disc from further rotation by the act of inertia when power rotation of the cam disc is stopped, said brake being resiliently urged into an inoperative position by a resilient means.

24. A belt making machine comprising a casing, a source of belt links at one end of said casing, 75 a feeder slidably mounted on said casing for suc-

cessively carrying the belt links away from said source to the other end of said casing, means at the other end of said casing for supporting a belt being formed with its aligned slots on a horizontal plane aligned with the path of movement of said feeder so that said feeder will enter said slots and position the carried belt link in the aligned slots, a pilot slidably mounted on said casing to traverse a path parallel to that traversed by said feeder and to enter the aligned slots of the belt in advance of said feeder to condition the aligned slots for the entrance of said feeder and the carried belt link, and means for oscillating said feeder and said pilot to and fro between said source of belt links and said belt supporting means and in timed synchronism so that said pilot always enters the aligned slots of the belt being formed in advance of said feeder and the belt link carried thereby, said oscillating means comprising a continuously rotating cam disc, and arms each having one of their ends eccentrically pivotally connected to said cam disc and their other ends pivotally connected respectively to said feeder or said pilot, said cam disc being continuously rotated by an outside source of power.

25. In a belt machine for forming a belt of interengaged links and having a rotating cam disc, a punch for forming the links from a continuous strip of material, comprising a bed, a fixed die member mounted on said bed, a movable die member above said fixed die member, means slidably supporting said movable die member for movement toward and away from said fixed die member, resilient means urging said movable die member toward said fixed die member with sufficient pressure to cut the links from a strip of material passing between said die members, and mechanism operated by said cam disc for releasably retaining said movable die member in a raised position off said fixed die member.

26. In a belt machine for forming a belt of interengaged links and having a rotating cam disc, a punch for forming the links from a continuous strip of material, comprising a bed, a fixed die member mounted on said bed, a movable die member above said fixed die member, means slidably supporting said movable die member for movement toward and away from said fixed die member, resilient means urging said movable die member toward said fixed die member with sufficient pressure to cut the links from a strip of material passing between said die members, and mechanism operated by said cam disc for releasably retaining said movable die member in a raised position off said fixed die member, the links being shaped to include a rounded head portion, a reduced neck portion and a body portion with one slot in said head portion and two slots in said body portion, said die members being arranged to form the free end of the body portion of one link severing that link from the continuous strip and to form the rounded head portion, the reduced neck portion and the slots of the next link for each movement of said movable die member toward said fixed die member.

27. In a belt machine for forming a belt of interengaged links and having a rotating cam disc, a punch for forming the links from a continuous strip of material, comprising a bed, a fixed die member mounted on said bed, a movable die member above said fixed die member, means slidably supporting said movable die member for movement toward and away from said fixed die member, resilient means urging said movable die member toward said fixed die member with suffi-

cient pressure to cut the links from a strip of material passing between said die members, and mechanism operated by said cam disc for releasably retaining said movable die member in a raised position off said fixed die member, the links being shaped to include a rounded head portion, a reduced neck portion and a body portion with one slot in said head portion and two slots in said body portion, said die members being arranged to form the free end of the body portion of one link severing that link from the continuous strip and to form the rounded head portion, the reduced neck portion and the slots of the next link for each movement of said movable die member toward said fixed die member, a source of continuous strip material, and means operated in synchronization with said movable die member to draw said strip of material from said source during the time said movable die is raised to advance the partially formed link into position to have the free end of its body portion formed on the next movement of said movable die member toward said fixed die member.

28. In a belt machine for forming a belt of interengaged links and having a rotating cam disc, a punch for forming the links from a continuous strip of material, comprising a bed, a fixed die member mounted on said bed, a movable die member above said fixed die member, means slidably supporting said movable die member for movement toward and away from said fixed die member, resilient means urging said movable die member toward said fixed die member with sufficient pressure to cut the links from a strip of material passing between said die members, and mechanism operated by said cam disc for releasably retaining said movable die member in a raised position off said fixed die member, the links being shaped to include a rounded head portion, a reduced neck portion and a body portion with one slot in said head portion and two slots in said body portion, said die members being arranged to form the free end of the body portion of one link severing that link from the continuous strip and to form the rounded head portion, the reduced neck portion and the slots of the next link for each movement of said movable die member toward said fixed die member, a source of continuous strip material, and means operated in synchronization with said movable die member to draw said strip of material from said source during the time said movable die is raised to advance the partially formed link into position to have the free end of its body portion formed on the next movement of said movable die member toward said fixed die member, and a resiliently supported pressure plate carried by said movable die member for clamping said strip of material against the top face of said fixed die member during a link forming operation.

29. In a belt machine for forming a belt of interengaged links and having a rotating cam disc, a punch for forming the links from a continuous strip of material, comprising a bed, a fixed die member mounted on said bed, a movable die member above said fixed die member, means slidably supporting said movable die member for movement toward and away from said fixed die member, resilient means urging said movable die member toward said fixed die member with sufficient pressure to cut the links from a strip of material passing between said die members, and mechanism operated by said cam disc for releasably retaining said movable die member in a raised position off said fixed die member, said

resilient means comprising an expansion spring operating between the top face of said movable die member and a fixed part of said punch.

30. In a belt machine for interengaging a plurality of links in continuation of one end of a pre-formed tongue member and having a casing enclosing a rotating cam disc and mechanism for supporting the tongue member in a position to have the links interengaged therewith, a magazine supported above the casing for containing a plurality of the pre-formed tongue members, comprising a container for the tongue members having a bottom wall, spaced end walls and front and back walls, said bottom wall being formed adjacent one end wall with an opening above the tongue supporting mechanism through which the tongues are to be individually dropped, cylindrical keys turnably supported within said container adjacent the said one end wall, a floating plate within said container and between said keys and the contained tongue members, resilient means in said container urging the contained tongue members against said floating plate and said floating plate against said keys, said keys having flat surfaces turned away from said floating plate, mechanism operated by the cam disc for turning said keys to face said flat surfaces toward said floating plate permitting said floating plate and the contained tongue members to move slightly toward said keys, and means operated by said keys for engaging between the adjacent faces of the tongue member in contact with said floating plate and the next adjacent tongue member to retain said next adjacent tongue member and the tongue members therebehind from moving toward said floating plate so that the tongue member in contact with said floating plate will be free to drop through said opening.

31. In a belt machine for interengaging a plurality of links in continuation of one end of a pre-formed tongue member and having a casing enclosing a rotating cam disc and mechanism for supporting the tongue member in a position to have the links interengaged therewith, a magazine supported above the casing for containing a plurality of the pre-formed tongue members, comprising a container for the tongue members having a bottom wall, spaced end walls and front and back walls, said bottom wall being formed adjacent one end wall with an opening above the tongue supporting mechanism through which the tongues are to be individually dropped, cylindrical keys turnably supported within said container adjacent the said one end wall, a floating plate within said container and between said keys and the contained tongue members, resilient means in said container urging the contained tongue members against said floating plate and said floating plate against said keys, said keys having flat surfaces turned away from said floating plate, mechanism operated by the cam disc for turning said keys to face said flat surfaces toward said floating plate permitting said floating plate and the contained tongue members to move slightly toward said keys, and means operated by said keys for engaging between the adjacent faces of the tongue member in contact with said floating plate and the next adjacent tongue member to retain said next adjacent tongue member and the tongue members therebehind from moving toward said floating plate so that the tongue member in contact with said floating plate will be free to drop through said opening, said resilient means comprising a follower in said container between the contained tongue members and the

other end wall, and expansion springs operating between the adjacent faces of said follower and the said other end wall.

32. In a belt machine for interengaging a plurality of links in continuation of one end of a pre-formed tongue member and having a casing enclosing a rotating cam disc and mechanism for supporting the tongue member in a position to have the links interengaged therewith, a magazine supported above the casing for containing a plurality of the pre-formed tongue members, comprising a container for the tongue members having a bottom wall, spaced end walls and front and back walls, said bottom wall being formed adjacent one end wall with an opening above the tongue supporting mechanism through which the tongues are to be individually dropped, cylindrical keys turnably supported within said container adjacent the said one end wall, a floating plate within said container and between said keys and the contained tongue members, resilient means in said container urging the contained tongue members against said floating plate and said floating plate against said keys, said keys having flat surfaces turned away from said floating plate, mechanism operated by the cam disc for turning said keys to face said flat surfaces toward said floating plate permitting said floating plate and the contained tongue members to move slightly toward said keys, and means operated by said keys for engaging between the adjacent faces of the tongue member in contact with said floating plate and the next adjacent tongue member to retain said next adjacent tongue member and the tongue members therebehind from moving toward said floating plate so that the tongue member in contact with said floating plate will be free to drop through said opening, said floating plate having its top end curled about a pin, said pin being longer than said floating plate is wide and having its ends resting on the top edges of said front and rear walls floatingly supporting said floating plate.

33. In a belt machine for interengaging a plurality of links in continuation of one end of a pre-formed tongue member and having a casing enclosing a rotating cam disc and mechanism for supporting the tongue member in a position to have the links interengaged therewith, a magazine supported above the casing for containing a plurality of the pre-formed tongue members, comprising a container for the tongue members having a bottom wall, spaced end walls and front and back walls, said bottom wall being formed adjacent one end wall with an opening above the tongue supporting mechanism through which the tongues are to be individually dropped, cylindrical keys turnably supported within said container adjacent the said one end wall, a floating plate within said container and between said keys and the contained tongue members, resilient means in said container urging the contained tongue members against said floating plate and said floating plate against said keys, said keys having flat surfaces turned away from said floating plate, mechanism operated by the cam disc for turning said keys to face said flat surfaces toward said floating plate permitting said floating plate and the contained tongue members to move slightly toward said keys, and means operated by said keys for engaging between the adjacent faces of the tongue member in contact with said floating plate and the next adjacent tongue member to retain said next adjacent tongue member and the tongue members therebehind from moving

toward said floating plate so that the tongue member in contact with said floating plate will be free to drop through said opening, studs extending from said keys through elongated slots formed in said one end wall, a tie member connecting said studs, and spring means urging said tie member into a position in which said keys will turn with the flat surfaces facing away from said floating plate.

34. In a belt machine for interengaging a plurality of links in continuation of one end of a pre-formed tongue member and having a casing enclosing a rotating cam disc and mechanism for supporting the tongue member in a position to have the links interengaged therewith, a magazine supported above the casing for containing a plurality of the pre-formed tongue members, comprising a container for the tongue members having a bottom wall, spaced end walls and front and back walls, said bottom wall being formed adjacent one end wall with an opening above the tongue supporting mechanism through which the tongues are to be individually dropped, cylindrical keys turnably supported within said container adjacent the said one end wall, a floating plate within said container and between said keys and the contained tongue members, resilient means in said container urging the contained tongue members against said floating plate and said

floating plate against said keys, said keys having flat surfaces turned away from said floating plate, mechanism operated by the cam disc for turning said keys to face said flat surfaces toward said floating plate permitting said floating plate and the contained tongue members to move slightly toward said keys, and means operated by said keys for engaging between the adjacent faces of the tongue member in contact with said floating plate and the next adjacent tongue member to retain said next adjacent tongue member and the tongue members therebehind from moving toward said floating plate so that the tongue member in contact with said floating plate will be free to drop through said opening, said means operated by said keys comprising vertical shafts rotatively supported on said container outside of said front and rear walls, metallic members clamped on said shafts and having tail portions resting against said keys and beveled nose portions aligned with the adjacent faces of the first two tongue members with relation to said floating plate but normally withdrawn from between said faces, and resilient means turning said vertical shafts to positions in which said tail portions rest against said keys.
